SHEET FEEDING APPARATUS

Leonard Baker, Hillsdale, N. J., and Leo C. Williams, Pearl River, N. Y., assignors to Dexter Folder Company, Pearl River, N. Y., a corporation of New York

Application July 16, 1940, Serial No. 345,744

27 Claims.

(Cl. 271—62)

This invention relates to sheet feeders and while capable of general use is particularly adapted for embodiment in feeders for feeding sheets of tin, black iron, aluminum and the like, to printing presses, coating and varnishing machines, buffing and cleaning machines, shears and slitters, and various other instrumentalities for acting on such sheets.

In the United States Patent No. 1,442,718 granted January 16, 1923, to John W. Free, there is disclosed a sheet feeder having a hydraulically actuated pile elevator. This hydraulically actuated pile elevator includes a vertically disposed ram directly connected with the pile support, which is objectionable by reason of the requirement for a well or cylinder for the ram which well or cylinder obviously must be arranged in the foundation of the building or structure wherein the sheet feeder is installed, thus limiting the installation of the sheet feeder to a certain definite location only. This type of hydraulically actuated pile elevator is further objectionable for the reason that the pile of sheets must be positioned in the center of the pile support, because any shifting of the pile out of said position would cause binding of the vertically disposed ram in the well or cylinder with resulting faulty operation of the feeder.

It is accordingly one object of the present invention to provide a sheet feeder having a pile elevator which is actuated by improved hydraulic mechanism that does not require a vertically disposed ram directly connected with the pile support and thus overcomes the above mentioned objections.

Another object of the present invention is to provide a sheet feeder having a pile elevator which is actuated by improved hydraulic mechanism so arranged and constructed that said mechanism is disposed wholly within the sheet feeder.

Another object of the present invention is to provide a sheet feeder having a pile elevator which is intermittently raised by improved hydraulic mechanism and controlled pneumatically through movement of the pile and removal of sheets therefrom.

Another object of the present invention is to provide improved hydraulic mechanism for actuating a pile elevator of the type that is suspended at four corners by cables, chains or other flexible elements.

Another object of the present invention is to provide a sheet feeder having improved hydraulic mechanism for intermittently raising the pile

elevator and for rapidly lowering and raising the pile elevator.

These and other objects of the present invention will appear as the following description thereof proceeds and in order to more clearly understand said invention reference may be had to the accompanying drawings which illustrate two embodiments of said invention.

In said drawings:

Fig. 1 is a side elevation of a sheet feeder constituting one embodiment of the present invention;

Fig. 2 is a front elevation of said feeder, showing hydraulic pile elevator actuating means;

Fig. 3 is a top plan view of the feeder shown in Figs. 1 and 2;

Fig. 4 is a horizontal sectional view on the line 4—4 of Fig. 1;

Figs. 5 and 6 are enlarged side elevations of brackets forming part of an auxiliary frame for supporting certain parts of the feeder as a unit;

Fig. 7 is an enlarged side elevation, partly in section, of control means for the feeder starting and stopping device illustrated in Figs. 2, 3 and 6;

Fig. 8 is an enlarged view illustrating diagrammatically the complete hydraulic pile elevating system and control means therefor illustrated in Figs. 1, 2 and 4;

Figs. 9 and 10 are enlarged diagrammatic views of the valve illustrated in Fig. 8;

Fig. 11 is a fragmentary side elevation partly in section, of mechanism for manually operating the valve illustrated in Figs. 8, 9 and 10;

Figs. 12 and 12^a are complementary side elevations of a sheet feeder constituting another embodiment of the present invention;

Figs. 13 and 13^a are complementary top plan views of the sheet feeder illustrated in Figs. 12 and 12^a and showing another hydraulic pile elevator actuating means embodying the present invention;

Fig. 14 is a fragmentary rear elevation showing the driving mechanism for the feeder illustrated in Figs. 12 to 13^a;

Fig. 15 is an enlarged end view, partly in section, of the hydraulic pile elevator actuating means shown in Fig. 13^a looking from the left thereof;

Fig. 16 is an enlarged view illustrating diagrammatically the complete hydraulic pile elevating system and control means therefor shown in Figs. 13 and 13^a;

Figs. 17 and 18 are enlarged vertical sectional

views of the pile elevator pneumatic control means illustrated in Figs. 12, 13 and 16;

Figs. 19 and 20 are enlarged diagrammatic views of the control valve illustrated in Fig. 16;

Fig. 21 is an enlarged end view, partly in section, of the mechanism shown in Figs. 13 and 16 for manually operating the control valve;

Fig. 22 is a horizontal sectional view on the line 22-22 of Fig. 21; and

Fig. 23 is a fragmentary rear elevation of the 10 hydraulic pile elevator actuating means.

Referring first to Figs. 1 to 11 inclusive, which illustrate one embodiment of the present invention and wherein like reference characters designate like parts throughout the several views, the various movable parts of the feeder therein shown as well as certain stationary parts thereof may be mounted on a frame of any suitable construction and the movable parts may be actuated or driven by any suitable means. Said frame and driving means are preferably constructed as follows.

As shown in Figs. 1 to 4, the feeder frame is comprised by front uprights indicated broadly at 5 and rear uprights 6 connected together by side members indicated broadly at 7. These front uprights 5 and side members 7 are each comprised by a pair of steel plates 8, 9 and 10, 11 respectively, the plates 10, 11 being secured to or formed integrally with the plates 8, 9 at the tops thereof. The plates 8, 9 and 10, 11 of each front upright 5 and side member 7 are spaced apart and bolted together by spacers 12 and bolts 13 located at suitable points along said plates. The upper ends of the rear uprights 6 extend between the plates 10, 11 and are bolted or otherwise suitably secured thereto. The uprights 5 and 6 are bolted or otherwise suitably secured to the machine foundation, the front uprights 5 being connected together by cross beams 14 and 15. The cross beam 14 is bolted or otherwise suitably secured to the plates 9. The cross beam 15 is bolted or otherwise suitably secured at opposite ends thereof to pairs of spaced brackets 16, 16 and 16', 16' which, in turn, are bolted or otherwise suitably secured to the plates 9 of the front uprights 5. It will thus appear that the spaced plates 8, 9 and 10, 11 and the rear uprights 6 form a frame of rigid construction with a minimum amount of material.

The cross beam 14 has bolted or otherwise suitably secured thereto the lower end of a metal apron or plate 17 against which the front side of a supply or pile of metal or other sheets 18 bears during elevation of the same by mechanism to be hereinafter described. The upper end of the metal apron or plate 17 is bolted or otherwise suitably secured to a cross beam 19 which forms part of an auxiliary frame indicated broadly at 20 (Figs. 1, 2, 3, 5 and 6). This auxiliary frame 20 is disposed between the front uprights 5 near the tops thereof and includes side brackets 21 and 22 which are bolted or otherwise suitably secured to the plates 9 and connected together by the cross beam 19.

Referring now more particularly to Figs. 1 and 6, the drive for the feeder is preferably comprised by a chain 23 driven from any suitable source of power (not shown) and passing around a sprocket 24 which is fixed on the outwardly projecting end of a short shaft 25. This short shaft 25 is journaled in suitable bearings in the plates 8, 9 of the adjacent front upright 5 and in the side bracket 21 through which said

shaft extends. Disposed within the bracket 21 and fixed on the opposite end of the short shaft 25 is a spur pinion 26 which meshes with a spur gear 27 also disposed within said bracket and fixed on a cam shaft 28 projecting therein. This cam shaft 28 extends transversely of the feeder and is journaled in suitable bearings in the side brackets 21, 22 of the auxiliary frame 20. The cam shaft 28 is utilized to operate various parts of the feeder to be hereinafter described. The pile of sheets 18 is supported on a pile elevator which is operated by hydraulically actuated means. Said pile elevator and hydraulically actuated operating means therefor are, in accordance with one aspect of the present invention, preferably mounted and constructed as follows.

Bolted or otherwise suitably secured to the top of cross beam 15 adjacent one end thereof is a tank 29 (Figs. 1, 2, 4 and 8) adapted to contain a supply of oil, water or other suitable motive fluid as indicated at 30. Connected with the tank 29 and extending therein is one end of a conduit 31 the opposite end of which is connected, as by a connector 32, with the housing 33 of a plunger pump indicated broadly at 34. This plunger pump 34 is bolted or otherwise suitably secured to a metal shelf 35 and, as hereinafter described, is utilized to impart intermittent raising movement hydraulically to a pile elevator and pile of sheets 18 thereon. The shelf 35 is bolted or otherwise suitably secured at its rear end to the cross beam 15, the front end of said shelf being supported by a pair of rods 36 which are connected with the shelf and adjustably secured at their lower ends in brackets 37 that are bolted or otherwise suitably secured to the lower cross beam 14.

Slidably mounted in the housing 33 of pump 34 is a plunger 38 (Fig. 8) which projects upwardly through the housing and is provided on the upper end with a head 39. The housing 33 has bolted or otherwise suitably secured to the top thereof a cover plate 40 having a tubular guide 41 formed on opposite sides thereof for the upper end of the plunger 38. The lower end of the plunger 38 extends into a chamber 42 provided in the housing 33 and which communicates with the conduit 31 through a port 43 formed in said housing. A spring 44, encircling the upper portion of the tubular guide 41 and interposed between the cover plate 40 and the plunger head 39, normally tends to raise the plunger 38.

Reciprocating pumping action is imparted to the plunger 38 by the spring 44 and an eccentric 45 adapted to engage the head 39 of said plunger. This eccentric 45 is fixed on one end of the shaft 46 of a combined air and vacuum pump 47 (Figs. 2 and 4) which is bolted or otherwise suitably secured to the shelf 35. Fixed on the opposite end of the shaft 46 is a sprocket 48 around which passes a chain 49 that also passes around a sprocket 50 that is fixed on the armature shaft 51 of an electric motor 52 connected with a suitable source of current and controlled for starting and stopping purposes by suitable switch means (not shown). The electric motor 52 is bolted or otherwise suitably secured to the cross beam 15. It will thus appear that through rotation of the eccentric 45 by the described driving connections therefor with the motor 52, and expanding action of the spring 44, the plunger 38 will be raised and lowered during each revolution of the eccentric 45.

Under these conditions fluid is intermittently drawn from the tank 29 through the conduit 31,

connector 32, and port 43 into the chamber 42 of housing 33. Fluid so drawn into the chamber 42 is intermittently forced therefrom and directed under pressure into a cylinder 53 at the left hand end thereof as viewed in Figs. 2 and 8. For this purpose the housing 33 of pump 34 has connected therewith, as by a connector 54 (Fig. 8), one end of a conduit 55 which communicates with the chamber 42 through a port 56 formed in the housing. The opposite end of the conduit 55 is connected, as by a fitting 57, with one end of a conduit 58 the opposite end of which is connected with a cover plate 59 that is bolted or otherwise suitably secured to the cylinder 53. The conduit 58 communicates with the interior of the cylinder 53 through a port 60 formed in the cover plate 59. The connector 32 for conduit 31 is provided with an inwardly opening spring pressed ball check valve 61 (Fig. 8) to prevent return flow of fluid from the chamber 42. The connector 54 for conduit 55 is provided with an outwardly opening spring pressed ball check valve 62 to prevent return flow of fluid from the cylinder 53 through said conduit.

As shown in Fig. 2, the cylinder 53 is arranged horizontally in the sheet feeder and formed with brackets 63 and 64 through the medium of which said cylinder is bolted or otherwise suitably secured to the lower cross beam 14 at one end thereof. Due to the required length of the cylinder 53 the left hand portion thereof, as viewed in Fig. 2, projects beyond the adjacent front upright 5 through suitable openings formed in the plates 8, 9 of said upright. Slidably mounted in the cylinder 53 is a hydraulically actuated piston 65 (Fig. 8) having a piston rod 66. The piston rod 66 projects through a cylinder head 67 bolted or otherwise suitably secured to said cylinder, and through and outwardly beyond a packing gland 68 adjustably secured to said cylinder head. Secured in any suitable manner to the outwardly projecting end of the piston rod 66 is a yoke 69 (Fig. 2) having journaled thereon as at 70 a sheave 71 provided with suitable grooves for the reception of four pile elevator supporting cables 12, 13, 74 and 75 (Figs. 1 to 4). These cables 12, 13, 74 and 75 have corresponding ends anchored as at 16, 17, 18 and 19 in a block 80 (Figs 1 and 2) which is bolted or otherwise suitably secured to the cross beam 14 and further braced by the bracket 63 of cylinder 53.

As shown in Fig. 2 the cables 12, 13, 74 and 75 extend from the block 80 beneath and along the cylinder 53 through suitable openings formed in the brackets 63, 64 and in a guide block 81, and then pass around the sheave 71 on yoke 69. The guide block 81 is bolted or otherwise suitably secured to the cross beam 14. From the sheave 71 the cables 12, 13, 74 and 75 extend back over the cylinder 53, and then pass under and around a suitably grooved sheave 82 which is disposed between the brackets 16, 16 and journaled on a pin 83 secured in any suitable manner in said brackets. The sheave 82 and cables 12, 13, 74 and 75 passing around the same project into the space between the plates 8, 9 of the adjacent front upright 5 through a suitable opening provided in the plate 9. From the sheave 82 the cables 72 and 73 extend upwardly between the plates 8, 9 to the top of the feeder at which point said cables pass around a suitably grooved sheave 84 (Figs. 1 to 3) which is disposed between said plates and journaled thereon as at 85. From the sheave 84 the cable 72 extends rearwardly between the plates 10, 11 of the ad-

jacent side member 7 and then passes around a suitably grooved sheave 86 (Figs. 1 and 3) which is disposed between said plates and journaled thereon as at 87. The cables 72 and 73 then extend downwardly from the sheaves 86 and 84 respectively, and have their lower free ends connected in any suitable manner to the rear and front ends, respectively, of a pile elevator side member 88.

The cables 74 and 75 (Fig. 2) which pass around the sheave 82 as previously described, extend transversely of the feeder to the opposite side thereof and then pass under and around a suitably grooved sheave 89 which is disposed between the brackets 16, 16' and journaled on a pin 90 secured in any suitable manner in said brackets. The sheave 89 and cables 74, 75 passing around the same project into the space between the plates 8, 9 of the adjacent upright 5 through a suitable opening provided in the plate 9. From the sheave 89 the cables 74 and 75 extend upwardly between the plates 8, 9 to the top of the feeder at which point said cables pass around a suitably grooved sheave 91 (Figs. 2 and 3) which is disposed between said plates and journaled thereon as at 92. From the sheave 91 the cable 74 extends rearwardly between the plates 10, 11 of the adjacent side member 7 and then passes around a suitably grooved sheave 93 (Fig. 3) which is disposed between said plates and journaled thereon as at 94. The cables 74 and 75 (Fig. 3) then extend downwardly from the sheaves 93 and 91, respectively, and have their lower free ends connected in any suitable manner to the rear and front ends respectively, of a pile elevator side member 95.

The pile elevator comprises the side members 88 and 95 and cross members 96 (Fig. 1) engaged over said side members and adapted to receive a pile board 97 which, together with the pile of metal or other sheets 18 is positioned on said elevator through the rear of the feeder when the elevator is lowered by means for this purpose hereinafter described. It is to be noted, that due to the particular arrangement of the sheaves 84, 86 and 91, 93 the downwardly extending portions of the cables 73 and 75 are disposed between the plates 8, 9 of the front uprights 5 and beyond the pile guiding plate 17, and the downwardly extending portions of the cables 12 and 14 are disposed well to the rear of the feeder. In this manner both sides of the feeder frame are unobstructed, enabling positioning of the pile board 97 and pile of sheets 18 on the pile elevator through either side of the feeder if desired.

It will thus appear that when fluid is intermittently forced under pressure into the left hand end of the cylinder 53 and against the left face 60 of the piston 65 as viewed in Fig. 8, by the intermittent action of the plunger pump 34, the piston 65 will be moved step by step toward the right hand end of said cylinder. During this movement fluid on the opposite side of the piston 65 will be discharged from the cylinder 53 and returned to the tank 29 in a manner to be hereinafter described. As the piston 65 moves step by step toward the right, the piston rod 66, yoke 69 and sheave 71 will also move toward the right and those portions of the cables 12, 13, 74 and 75 extending from the block 80, around the sheave 71, to the sheave 82 will be lengthened. This obviously shortens those portions of the cables 12, 13, 74 and 75 between the sheaves 84, 86, 91 and 93 and the elevator side members 88 and 95 re-

sulting in intermittent raising of the elevator and pile of sheets thereon. The piston rod 66 is guided for right line movement by a pair of spaced guide brackets 98 (Fig. 2) which are bolted or otherwise suitably secured to the lower cross beam 14 and provided with suitable grooves 99 slidably engaged by the yoke 69. It will be noted that since the cables 72, 73, 74 and 75 are anchored stationary at one end in the block 80, then extend from said block beneath the cylinder 53, around the sheave 11, and then back over the cylinder, a movement twice that of the piston 65 will be imparted to the pile elevator, thereby enabling employment of a relatively shorter cylinder and piston.

The elevator and pile of sheets 18 thereon are raised intermittently as the sheets are fed off the top of said pile by sheet separating and forwarding means hereinafter described, and to keep the top of said pile at a predetermined level for the operation of said means, the elevator and its operating mechanism are controlled pneumatically by compressed air actuated means of the general type disclosed in the United States Patent No. 2,156,648 granted May 2, 1939, to Leonard Baker, George A. Martin and Leo C. Williams. This pneumatic control means and source of compressed air therefor is preferably mounted, constructed and operated as follows.

Bolted or otherwise suitably secured on the plates 11 of side members 7 are brackets 100 to which are pivoted, as at 101, a frame indicated broadly at 102 (Figs. 1 and 3). This frame 102 comprises side members 103 and a rear cross member 104 mounted on said side members and adjustable therewith to various positions. The frame 102 is supported at the rear thereof by pins 105 secured in the rear uprights 6. Secured to, and adjustable along, the rear cross member 104 is a bracket 106 having mounted thereon a vertically adjustable valve housing 107 (Figs. 3 and 8). Connected with the valve housing 107 is one end of a flexible conduit 108 the opposite end of which is connected with one end of a conduit 109. The opposite end of this conduit 109 is secured in and communicates with a conduit 110 (Fig. 5) formed in the side bracket 22 of the auxiliary frame 20.

Air under pressure is continuously maintained in the conduits 108, 109 and 110 by the pump 47 which, as previously described, is driven by the electric motor 52 through the described driving connections between said motor and said pump. For this purpose, the air pressure side of the pump 47 has connected therewith one end of a conduit 111 (Figs. 2 and 4) the opposite end of which is connected with a compressed air tank 112 through the medium of a flexible conduit 113. The compressed air tank 112 is supported at opposite ends thereof by angle bars 114 (Figs. 1 and 2) which are bolted or otherwise suitably secured to the cross beam 14 and extend forwardly therefrom. Displacement of the compressed air tank 112 from the angle bars 114 is prevented by clamps 115 which are engaged over the rims of said tank and bolted or otherwise suitably secured to said bars. The compressed air tank 112 has connected therewith one end of a flexible conduit 116 the opposite end of which is connected with the side bracket 22 and communicates with the conduit 110 formed therein (Figs. 2 and 5).

Slidably mounted in the housing 107 is a valve 117 the stem of which projects downwardly through the housing and is provided on the lower

end with a socket 118 in which is freely mounted a ball 119 of steel, glass or other non-yielding material that rests on the top of the pile of sheets 18 (Figs. 1 and 8). The valve 117 is provided with a reduced portion 120 and the valve housing 107 is provided in the bore thereof with a chamber 121. When the top of the pile of sheets 18 is at proper height the valve 117 through engagement of ball 119 with the pile will be positioned as shown in Fig. 8 wherein it will be noted that the reduced portion 120 of the valve is disposed slightly above chamber 121 so that air under pressure supplied in the valve housing and around the reduced portion of the valve by conduit 108 cannot reach the chamber 121.

As sheets are fed one after another from the top of the pile, and with ball 119 engaged therewith, the valve 117 will lower by gravity so that when a sufficient number of sheets have been so fed, the reduced portion 120 of the valve will extend or drop into the chamber 121 thus establishing communication between the latter and the conduit 108. Under these conditions, air under pressure will be delivered into a flexible conduit 122 having one end connected with the chamber 121 and the opposite end connected with one end of a conduit 123 (Figs. 2, 3 and 8). The opposite end of this conduit 123 is connected with a housing 124 at the bottom thereof, and said housing is secured to or formed integrally with a bracket 125 which is bolted or otherwise suitably secured to the plunger pump housing 33. Mounted in the housing 124 and projecting upwardly therethrough is a plunger 126 (Fig. 8) provided on the bottom thereof with a reduced portion 127 which normally engages a V-shaped bottom of the housing when no compressed air is being supplied therein through the conduit 123.

Extending over, and engageable by, the upper end of plunger 126 is one arm 128 of a bell crank detent 129 (Fig. 8) which is pivotally mounted on a pin 130 secured in any suitable manner on the bracket 125. The other arm 131 of bell crank detent 129 extends downwardly and has its lower end normally engaged with the head 39 of pump plunger 38 so that the latter is held in its lowermost position and against operation by the spring 44 and eccentric 45 to supply fluid under pressure to the cylinder 53. The length of the arm 131 is so proportioned that when the pump plunger 38 is actuated to its lowermost position by the high part of the eccentric 45, the head 39 on said plunger is disposed slightly below the lower end of the arm 131 to enable engagement of said arm with said head. Under operating conditions and when the pile elevator is at rest, the spring 44 holds the head 39 in engagement with the arm 131, and during each revolution of the eccentric 45 the high part of said eccentric imparts a slight downward movement to the pump plunger 38 sufficient to free the arm 131 from the head 39 but not sufficient to create a pumping action.

When air under pressure is admitted in the conduit 123, however, as previously described, said air enters the housing 124 and raises the plunger 126, thus swinging the bell crank detent 129 clockwise as viewed in Fig. 8 and disengaging the arm 131 from the head 39 upon subsequent engagement of the high part of the eccentric 45 with said head. When the arm 131 is disengaged from the head 39, the plunger pump 34 through expanding action of the spring 44 and continued rotation of the eccentric 45 will intermittently supply fluid under pressure into the left hand

end of the cylinder 53 as viewed in Figs. 2 and 8 from the tank 29 through the described conduits between said tank, said pump and said cylinder. The piston 65 will thus be actuated step by step toward the right, and through corresponding linear movement of the piston rod 66 and sheave 71, the cables 72, 73, 74 and 75 will, as previously described, raise the elevator and pile of sheets until the top of the pile is at the proper height.

As the pile thus raises, the valve 117 is lifted, thus raising the reduced portion 120 out of the chamber 121 and disconnecting the source of air under pressure from the housing 124. The plunger 126 and arm 128 then drop by gravity so that the lower end of the arm 131 is again engaged with the head 39 of pump plunger 38 to prevent further operation of the plunger pump 34. The eccentric 45 then rotates idly until further elevation of the pile is necessary at which time said pile will again be elevated as previously described. Excess swinging movement of the bell crank detent 129 in opposite directions is prevented by a pin 132 (Fig. 8) threaded in the bracket 125 and adapted to be engaged by the arm 131, and an adjusting screw 133 threaded in the free end of the arm 128 and adapted to engage the upper end of the housing 124. The adjusting screw 133 may be locked in adjusted position by a lock nut 134. When the elevator and pile of sheets 18 thereon are raised to the proper height and the plunger pump 34 is rendered inoperative as previously described, the fluid previously admitted into the cylinder 53 to intermittently raise said elevator is trapped therein by the ball check valve 62 which prevents return flow of the fluid, thus maintaining the elevator and pile of sheets in raised position.

The sheets of pile 18 are separated one after another at the rear by suction separating devices hereinafter referred to, but before this operation takes place the rear upper corners of the pile are winded to preliminarily separate the upper sheets of the pile by compressed air that is directed through vertically disposed blow pipes 135 (Fig. 1). These blow pipes 135 are carried in brackets 136 (Fig. 3) engaged over, and slideable along the rear cross member 104 of the pivoted frame 102. The upper ends of the blow pipes 135 have connected therewith corresponding ends of flexible conduits 137 the opposite ends of which are connected with a conduit 138 closed at its outer end and having an inner end secured in and communicating with a conduit 139 (Fig. 5) formed in the side bracket 22 of the auxiliary frame 20. This conduit 139 communicates with a port 140 formed in the side bracket 22 and opening outwardly therefrom through one side thereof. Spaced from the port 140 is another port 141 formed in the side bracket 22 and opening outwardly through the same side thereof as the port 140. This port 141 communicates with the conduit 110 which, as previously described, is continuously supplied with air under pressure from the compressed air tank 112 through the conduit 116.

Delivery of compressed air at the required predetermined intervals to the blow pipes 135 is effected by a rotary valve 142 (Figs. 2 and 3) loosely mounted on the cam shaft 28 and connected with a driving disk 143 that is secured to and continuously rotated by said cam shaft. The valve 142 is provided on the inner side thereof with an arcuate shaped port (not shown) which, through rotation of said valve, passes over the ports 140, 141 in the side bracket 22 once during

each cycle of operation of the feeder. This establishes communication between conduits 110, 139 (Fig. 5) and through the described connections for the conduit 139 with the blow pipes 135 compressed air is delivered through said pipes against the upper rear corner portions of the pile of sheets 18. When, through continued rotation of the valve 142, the ports 140, 141 no longer communicate with each other the air under pressure is prevented from entering the blow pipes 135 until the valve, in the next cycle of operation of the feeder, again rotates to bring said ports into register.

While the upper rear corner portions of the pile are being winded as just described, the top sheet of the pile is engaged and lifted by vacuum sheet separating devices comprised by cylinders 144 (Figs. 1 and 3) carried by the brackets 136, and suction cups 145 that are raised and lowered through the making and breaking of vacuum in said cylinders. These sheet separating devices are constructed and operated in the same manner as the sheet separating devices disclosed in the United States Patent No. 2,156,648 above referred to and need no detail description herein. It might be pointed out, however, that the cylinders 144 have connected therewith corresponding ends of flexible conduits 146 the opposite ends of which are connected, as by a tubular fitting 147, with the valve body 148 of a rotary valve mechanism indicated broadly at 149 (Figs. 2 and 3). This rotary valve mechanism 149 controls the making and breaking of vacuum in the cylinders 144 of the sheet separating devices and in sheet forwarding devices hereinafter referred to, and said valve mechanism is substantially the same in construction and operation as the valve mechanism disclosed in the United States Patent No. 2,156,648 above referred to except that in the present case separate valves 150 and 151 are provided for the sheet separating devices and the sheet forwarding devices.

The valve body 148 is secured to and supported by tubular shafts 152, 153 which extend transversely of the feeder and are secured at their opposite ends in the side brackets 21, 22 of the auxiliary frame 20. The tubular shaft 153 which is closed at both ends forms a vacuum conduit and communicates with the interior of the valve body 148. Vacuum is continuously created in the tubular shaft 153 and the valve body 148 by the pump 47, and for this purpose, the vacuum side of said pump has connected therewith one end of a flexible conduit 154 (Fig. 2). The opposite end of this flexible conduit 154 is connected with the side bracket 21 of the auxiliary frame 20 and communicates with a conduit 155 (Fig. 6) which is formed in said side bracket and connected with the tubular shaft 153.

Making and breaking of vacuum in the cylinders 144 of the sheet separating devices at predetermined intervals is effected by the rotary valve 150 that is connected with and rotated by a driving disk 156 (Fig. 2) fixed on the cam shaft 28 which extends loosely through the valve body 148. The rotary valve 150, during rotation of the same, connects and disconnects the cylinders 144 from the vacuum side of the pump 47 through the described connections for said cylinders with the valve body 148 and the described connections for the latter with said pump.

After the top sheet of the pile has been lifted at the rear thereof by the suction cups 145, the lifted sheet is winded to completely separate it from the next sheet therebelow by compressed

air that is delivered through vertically disposed blow pipes 157 (Fig. 1) carried in the brackets 136. The upper ends of the blow pipes 157 have connected therewith corresponding ends of flexible conduits 158 (Fig. 3) the opposite ends of which are connected with a conduit 159 that is closed at its outer end. The inner end of the conduit 159 is secured in and communicates with a conduit 160 (Fig. 5) formed in the side bracket 22 of the auxiliary frame 20. This conduit 160 communicates with a port 161 opening outwardly through the side of the side bracket 22 in which the ports 140, 141 are formed. Spaced from the port 161 is another port 162 which opens outwardly through the same side of the side bracket 22. The ports 161, 162 are disposed substantially 180 degrees apart from the ports 140, 141, and the port 162 communicates with the conduit 110 which, as previously described, is continuously supplied with air under pressure from the compressed air tank 112.

Delivery of compressed air at the required predetermined intervals to the blow pipes 157 is effected by the rotary valve 142 which, through continued rotation thereof, connects the ports 161, 162 so that air under pressure is delivered from the conduit 110 to the conduits 160, 159 and through the blow pipes 157. The compressed air delivered through the blow pipes 157 is directed between the separated sheet and the one therebelow so that said uppermost sheet is completely lifted from the pile. When, through continued rotation of the valve 142, the ports 161, 162 no longer communicate with each other, the air under pressure is prevented from entering the blow pipes 157 until the valve, in the next cycle of operation of the feeder, again rotates to bring the ports 161, 162 into register.

When the separated sheet has been wended it is forwarded from the pile by vacuum sheet forwarding devices comprised by cylinders 163 (Figs. 1 and 2) and suction cups 164 that are moved up and down relative to said cylinders through the making and breaking of vacuum therein. These sheet forwarding devices are also constructed and operated in the same manner as the sheet forwarding devices disclosed in the United States Patent No. 2,156,648 above referred to and need no detail description herein. It is pointed out, however, that the sheet forwarding devices have swinging movement to advance the sheets that have been separated from the pile 18 by the sheet separating devices. For this purpose, the cylinders 163 are secured to arms 165 which, in turn, are fixed on a rock shaft 166 that extends transversely of the feeder and is journaled in suitable bearings in the brackets 100. The sheet forwarding devices are rocked rearwardly by a cam 167 (Figs. 2, 3 and 7) that is fixed on and rotated by the cam shaft 28. This cam 167 engages a roller 168 journaled on a cam strap 169 extending over the cam shaft 28 and connected with an arm 170 that is fixed on the rock shaft 166. The sheet forwarding devices are rocked forwardly by a pull spring 171 having one end connected with the arm 170 and the opposite end connected in any suitable manner with the tubular shaft 153.

The making and breaking of vacuum in the cylinders 163 of the sheet forwarding devices is effected at proper intervals by the rotary valve 151 (Figs. 2 and 3), and for this purpose the cylinders 163 have connected therewith corresponding ends of flexible conduits 172 the opposite ends of which are connected, as by a tubular

fitting 173, with the valve body 148 of the rotary valve mechanism 149. The rotary valve 151 is loosely mounted on the cam shaft 28 and arranged at the side of the valve body 148 opposite that engaged by the rotary valve 150 which controls the making and breaking of vacuum in the cylinders 144 of the sheet separating devices. Rotation is imparted to the rotary valve 151 by a driving disk 174 which is connected with said valve and fixed on the cam shaft 28. The operation of the rotary valve 151 is so timed that vacuum is established in the cylinders 163 to move the suction cups 164 into engagement with the top sheet of the pile when the sheet forwarding devices have been swung rearwardly, and is maintained therein until said devices have completed their forward movement and delivered the sheet engaged thereby in proper position on a conveyor, to be herein-after described, at which time the vacuum is broken in said cylinders.

The sheets separated from the pile 18 by the sheet separating devices are taken by the sheet forwarding devices and delivered thereby to a sheet conveyor that advances the sheets to the machine 25 or other instrumentality with which the feeder is associated. This conveyor includes feed rollers 175, drop rollers 176, and conveyor tapes 177 passing around said feed rollers (Figs. 1 and 2). The feed rollers 175 are fixed in spaced relation on a shaft 178 which extends transversely of the feeder and is journaled in suitable bearings in the side brackets 21, 22 of the auxiliary frame 20. The shaft 178, the feed rollers 175 fixed thereon, and the conveyor tapes 177 passing around said rollers 30 are driven by suitable gearing including a gear 179 (Figs. 1 and 6) that is fixed on said shaft and disposed within the side bracket 21. This gear 179 meshes with a similar gear 180 also disposed within the side bracket 21 and which is secured to or formed integrally with the gear 26 that is rotated by the short drive shaft 25.

The drop rollers 176 are journaled on arms 181 (Fig. 2) fixed on a rock shaft 182 which extends transversely of the feeder and is journaled in 45 suitable bearings in the side brackets 21, 22 of the auxiliary frame 20. The drop rollers 176 are raised and lowered by a cam 183 secured to or formed integrally with the valve driving disk 174 and which engages a roller 184 journaled on an 50 arm 185 that is fixed on the rock shaft 182. An additional support and bearing for the rock shaft 182 is provided by the valve body 148.

If, for any reason, it is desired to temporarily interrupt the feed of sheets from the top of the 55 pile during the operation of the feeder, this is accomplished without having to disconnect the feeder from its source of power; without disturbing the timing between the feeder and the machine being fed thereby; and without failure of completion of feed of a sheet in process of delivery from the feeder. For this purpose, the side bracket 21 of the auxiliary frame 20 is provided with a relief valve 186 of the poppet type (Fig. 6) which communicates with the conduit 155 formed 60 in said bracket. This relief valve 186 is normally closed, as by a spring 187, to enable operation of the sheet separating and forwarding devices as above described. When the relief valve 186 is opened, however, the conduit 155 is open to atmosphere and thus prevents the operation of the sheet separating and forwarding devices.

Opening of the relief valve 186 is effected by a lever 188 that is pivotally mounted on a pin 189 secured in any suitable manner on the plate 9 of the adjacent front upright 5. The lower end of

the lever 188 is provided with an adjustable valve engaging member preferably in the form of a machine screw 190 threaded in said lever and locked in adjusted position by a lock nut 191. The upper end of the lever 188 has journalled thereon a roller 192 adapted to engage a cam 193 that is fixed on a rock shaft 194. This rock shaft 194 extends transversely of the feeder and is journalled in suitable bearings in the plates 8, 9 of the front uprights 5. The rock shaft 194 has fixed on the ends thereof handles 195 and by turning either of these handles in one direction the shaft 194, cam 193, and lever 188 may be swung to move the relief valve 186 to the dotted line position thereof shown in Fig. 6 thus opening the conduit 155 to atmosphere and preventing operation of the sheet separating and forwarding devices. Obviously when the rock shaft 194 is swung in the opposite direction by either of the handles 195 the relief valve 186 will close through the expanding action of the spring 187 so that the sheet separating and forwarding devices may again operate as above described. The cam 193 is provided in its periphery and at opposite ends thereof with recesses 196 adapted to be engaged by the roller 192 in order to hold the rock shaft 194 and cam 193 against accidental rotation when rocked to operative and inoperative positions. Rocking movement of the rock shaft 194 in opposite directions is limited by pins 197 (Fig. 1) secured in the plates 8 of the front uprights 5 and adapted to be engaged by lugs 198 formed on the handles 195.

Fixed on the rock shaft 194 is a stop arm 199 (Fig. 7) provided with shoulders 200 and 201 engageable with a lug 202 formed on the arm 203 of a bell crank 204. This bell crank 204 is pivotally mounted on a pin 205 secured in any suitable manner in the side bracket 21 (Fig. 2) and projecting inwardly therefrom. The other arm 206 of bell crank 204 has threaded in the free end thereof a machine screw 207 provided with a lock nut 207' and adapted to be engaged by the free end of the cam strap 169. The arm 206 of bell crank 204 has connected therewith one end of a pull spring 208 the opposite end of which is connected in any suitable manner with the tubular shaft 153. It will thus appear that the bell crank 204 is operated in one direction by the cam strap 169 to raise arm 203 of said bell crank and in the opposite direction by the spring 208 to lower said arm.

During normal operation of the feeder and for a major portion of each cycle thereof the bell crank 204 will be positioned as shown in full lines in Fig. 7 wherein it will be noted that the lug 202 on arm 203 is disposed in the path of travel of the shoulder 200 on stop arm 199 and thereby prevents actuation of the shaft 194, cam 193, lever 188 and relief valve 186 to interrupt the feeding of sheets from the top of the pile. However, when the sheet forwarding devices are swung to their extreme forward positions to deliver the sheet engaged thereby in proper position between the feed and drop rollers 175 and 176, the bell crank 204 is swung to the dotted line position thereof shown in Fig. 7 by the cam strap 169. The lug 202 on arm 203 is thus removed from the path of travel of the shoulder 200 on stop arm 199 at which time the shaft 194, the cam 193, the lever 188 and the relief valve 186 may be actuated to interrupt the feeding of sheets from the top of the pile. It will thus appear that the feeding of sheets from the top of the pile cannot be interrupted while a sheet is engaged by the sheet forwarding devices and

before it is delivered in proper position thereby on the conveyor.

When the shaft 194 is actuated as previously described to interrupt the feeding of sheets from the top of the pile, the stop arm 199 is moved to the dotted line position thereof shown in Fig. 7, and upon continued rotation of cam 167 to swing the sheet forwarding devices rearwardly, the bell crank 204 is again swung to the full line position thereof shown in Fig. 7 by the action of the spring 208. At this time the lug 202 on arm 203 is disposed in the path of travel of the shoulder 201 on stop arm 199 and thus prevents actuation of the shaft 194 in the opposite direction to start or restart the feeding operation except at the proper time as hereinafter described.

When it is desired to resume feeding operation, actuation of the shaft 194 is only possible when the sheet forwarding devices are swung to their extreme forward positions, and the arm 203 is lifted by the cam strap 169 to remove the lug 202 out of the path of travel of shoulder 201 on stop arm 199. At this time the relief valve 186 is again closed and upon continued rotation of the cam 167 the sheet forwarding devices move rearwardly and into proper position to act on the next sheet of the pile. When the sheet forwarding devices are swung rearwardly to act on the next sheet of the pile, the arm 203 is again lowered by the spring 208 to dispose the lug 202 in the path of travel of shoulder 200 on stop arm 199 so that the shaft 194 is again held against movement until the next sheet acted on by the sheet forwarding devices is delivered between the feed and drop rollers 175, 176. It will thus appear that through the described control for the relief valve 186, actuation of said valve to start or stop the feeding of sheets is only possible at the same predetermined point in each cycle of operation of the feeder thus always maintaining the proper timed relation between said feeder and the machine with which it is associated.

The feeder is provided with mechanism for rapidly lowering and raising the elevator so that a supply of sheets may be placed on said elevator and moved into proper position for feeding. This mechanism is also utilized to reload the feeder and, in accordance with the present invention, is preferably constructed, operated and controlled as follows. Bolted or otherwise suitably secured to the cross beam 15 and disposed between the fluid supply tank 29 and the electric motor 52 is a rotary fluid pump 209 (Figs. 4 and 8). This rotary fluid pump 209 is a constant displacement pump and is driven continuously and at constant speed by the electric motor 52 through a coupling 210 connecting the armature shaft 51 of said motor with the shaft 211 of said pump. Connected with the intake side of the rotary fluid pump 209 is one end of a conduit 212 the opposite end of which is connected with and extends into the fluid supply tank 29. Upon rotation of the rotary fluid pump 209 fluid is drawn from the supply tank 29 through the conduit 212 and forced out through a conduit 213 having one end connected with the exhaust side of said pump. The opposite end of this conduit 213 is connected with the housing 214 of a fluid controlling valve unit indicated broadly at 215 which is bolted or otherwise suitably secured to the fluid supply tank 29 at the top thereof. The housing 214 of valve unit 215 has formed therein chambers and passages such as shown, for example, in Figs. 8, 9 and 10 for

receiving and distributing the fluid under pressure to either end of the cylinder 53 or back to the fluid supply tank 29 as hereinafter described.

The end of the conduit 213 connected with the housing 214 communicates with a chamber 216 formed in said housing. This chamber 216 is connected, as by suitably spaced passages 217, 218 with a cylindrical bore 219 formed in the housing 214 and having one end opening outwardly through one side of the housing and the opposite end opening into a chamber 220 also formed in said housing. The cylindrical bore 219 is further connected with the chamber 220 by suitably spaced passages 221 and 222. Surrounding the cylindrical bore 219 and suitably spaced therealong are annular passages 223 and 224. Connected with the housing 214 and communicating with the annular passage 223 in said housing is one end of a conduit 225 the opposite end of which is connected with the fitting 57 and communicates with the piston chamber of the cylinder 53 through the conduit 58 and port 60. The other annular passage 224 in the housing 214 has connected therewith one end of a conduit 226 the opposite end of which is secured in the cylinder 53 at the right hand end thereof (Figs. 2 and 8) and communicates with the piston chamber of said cylinder through a port 227. Connected with the chamber 220 in the housing 214 is one end of a conduit 228 the opposite end of which is connected with and extends into the fluid supply tank 29.

Fitted for reciprocation in the cylindrical bore 219 of housing 214 is a valve member 229 provided at one end thereof with a reduced portion 230, and intermediate its ends with reduced portions 231, 232 and 233 of equal diameters. The reduced portions 231, 232 and 233, through the action of the fluid pressures against equal shoulders at opposite ends thereof, form balanced valve elements 234, 235 and 236. The valve element 235 is provided in its periphery with diametrically disposed, alternately arranged grooves or recesses 237 which extend midway across said valve element and open outwardly through opposite ends thereof.

Reciprocating motion is manually imparted to the valve member 229 and for this purpose, the outwardly projecting end of said valve member has pivotally connected therewith corresponding ends of spaced links 238 the opposite ends of which are pivotally connected with the free end of an arm 239 that is fixed on a rock shaft 240 (Figs. 1, 2, 4 and 8). This rock shaft 240 extends transversely of the feeder and is journalled in suitable bearings in the plates 9 of the front uprights 5. Fixed on one end of the rock shaft 240 and disposed between the plates 8, 9 of one of the front uprights 5 is an arm 241 (Figs. 4 and 11) having pivotally connected therewith the lower end of a connecting link 242. The upper end of the connecting link 242 is pivotally connected with one arm 243 of a bell crank 244 that is also disposed between the plates 8, 9 of the adjacent front upright 5 and pivotally mounted on a pin 245 secured in any suitable manner on the plate 9 thereof. Pivotally connected with the other arm 246 of bell crank 244 is the front end of a rod 247 which extends along one side of the feeder to the rear thereof and passes through a suitable opening formed in the adjacent rear upright 6. The rear end of rod 247 has fixed thereon a rod manipulating knob or handle 248.

During normal operation of the feeder and 75

while intermittent raising of the elevator and pile of sheets thereon is effected by the plunger pump 34, the valve member 229 will be positioned as shown in Fig. 8 wherein it will be noted that the 5 annular passage 223 in the housing 214 is closed by the valve element 234; that the annular passage 224 is closed by the valve element 235 except for the grooves or recesses 237 in said valve element which at this time communicate with 10 said annular passage; and that the chamber 216 in said housing is in communication with the chamber 220 through the reduced portion 233 of valve member 229 and through the passage 218 and 222. Under these conditions fluid under 15 pressure forced into the chamber 216 by the rotary pump 209 cannot enter the conduit 225 or the conduit 226 to effect actuation of the piston 65 in cylinder 53 but, instead, flows from the chamber 216 into the chamber 220 and returns 20 to the fluid supply tank 29 through the conduit 228. If, at this time, fluid should enter the grooves or recesses 237 at the left hand end of the valve element 235 through the passage 217 and reduced portion 231 of valve member 229, said fluid will flow into the annular passage 224 and out again through the grooves or recesses 237 at the right hand end of valve element 235 into the chamber 220 through the reduced portion 232 and passage 221. It will further be noted that 25 when the piston 65 is actuated by the fluid forced into the left hand end of cylinder 53 (Fig. 8) by the plunger pump 34 to intermittently raise the pile elevator and pile of sheets 18 thereon, the fluid in the right hand end of said cylinder 30 will be discharged from the cylinder by the piston and returned to the fluid supply tank 29 through the port 227, conduit 226, annular passage 224 and grooves or recesses 237 which, as 35 previously described, are open at this time to chamber 220. It will further be noted that with the valve member 229 in the position shown in Fig. 8 and closing of the annular passage 223 in housing 214 by the valve element 234, return flow of fluid from the left hand end of cylinder 53 40 through the conduit 225 is prevented by valve element 234 and the elevator and pile of sheets 45 thereon will thus be held in raised positions.

When it is desired to rapidly lower the pile elevator to load or reload it, the machine attendant standing at the back of the feeder grasps the knob or handle 248 and pulls the rod 247 rearwardly to the dotted line position D thereof shown in Fig. 11. When the rod 247 is moved as aforesaid, the valve member 229 through the described connections therefor with said rod will be shifted from the position thereof shown in Fig. 8 to the position thereof shown in Fig. 9 wherein it will be noted that the passage 218 in the housing 214 is closed by the valve element 236; that the annular passage 224 is closed to the passage 221 by the valve element 235 and opened to the passage 217 by the reduced portion 231 of valve member 229; and that the annular passage 223 is closed to the passage 217 by the 50 valve element 234 and opened to the chamber 220 by the reduced portion 230. Under these conditions, the fluid under pressure forced into the chamber 216 of housing 214 by the rotary pump 209 will flow continuously from said chamber through the passage 217, into the annular passage 224, through the conduit 226 and into the right hand end of cylinder 53 (Figs. 2 and 8) through the port 227. The fluid under pressure so forced into the cylinder 53 at the right hand end thereof acts on the right face of the piston 65

and moves said piston rapidly toward the left (Fig. 8) from the dotted line position toward the opposite end of said cylinder. During this movement the fluid previously admitted into the left hand end of the cylinder 53 is discharged from the cylinder by the piston and returned to the fluid supply tank 29 through the port 60, conduit 58, fitting 57, conduit 225, and annular passage 223 which, as previously described, is open at this time to the chamber 220.

As the piston 65 moves rapidly toward the left (Fig. 8) as previously described, the piston rod 66, yoke 69 and sheave 71 likewise move toward the left. Accordingly, those portions of the cables 72, 73, 74 and 75 extending from the block 80 to the sheave 82 (Fig. 2) will, by the weight of the elevator, become shortened resulting in lowering of the elevator and pile board 97 to the bottom of the feeder. As soon as the elevator and pile board 97 have reached the proper position for loading, the machine attendant moves the rod 247 forwardly to the full line position N thereof (Fig. 11) thereby shifting the valve member 229 back to the position shown in Fig. 8 at which time the flow of fluid under pressure into the cylinder 53 through the conduit 226 is interrupted by the valve element 235 and the piston 65 is stopped. The elevator is then loaded in the usual manner with a supply or pile of sheets positioned thereon through the rear or either side of the feeder. It might be mentioned at this time that when the elevator is rapidly lowered to loading position as previously described, the pile controlled valve 117, through lowering of the pile board 97 with the elevator, will drop to its lowermost position and close the conduit 108 so that air under pressure cannot enter the housing 107 and conduit 123 to render the plunger pump 34 operative while a supply or pile of sheets is being loaded on the elevator.

The elevator having been lowered and stopped in its proper position for loading or reloading, and the pile of sheets having been placed on the elevator, the latter and the pile of sheets are rapidly elevated until the top of the pile is brought into proper position for the normal sheet feeding operations. For this purpose, the machine attendant moves the rod 247 forwardly to the dotted line position U thereof (Fig. 11) to shift the valve member 229 from the position thereof shown in Fig. 8 to the position thereof shown in Fig. 10. In this position of the valve member 229 it will be noted that the passage 218 in the housing 214 is closed to the passages 221, 222 by the valve element 236 and the outer end of said valve member; that the annular passage 224 is closed to the passage 217 by the valve element 235 and opened to the passage 221 by the reduced portion 232 of the valve member; and that the annular passage 223 is closed to the chamber 220 by the valve element 234 and opened to the passage 217 by the reduced portion 231. Under these conditions, the fluid under pressure forced into the chamber 216 of housing 214 by the rotary pump 209 will flow continuously from said chamber through the passage 217, into the annular passage 223, through the conduit 225 and into the left hand end of cylinder 53 (Figs. 2 and 8) through the fitting 57, conduit 58 and port 60. The fluid under pressure so forced into the cylinder 53 at the left hand end thereof acts on the left face of the piston 65 and moves said piston rapidly toward the right to raise the elevator and pile of sheets thereon until the top of the pile reaches the proper level for feeding of the

sheets one after another therefrom. During this movement the fluid previously admitted into the right hand end of the cylinder 53 is discharged from the cylinder by the piston and returned to the fluid supply tank 29 through the port 227, conduit 226 and annular passage 224 which, as previously described, is open at this time to the chamber 220 through the passage 221.

When the top of the pile reaches the proper feeding level, and the pile controlled valve 117 is accordingly raised to its proper operating position thereby, the machine attendant again moves the rod 247 rearwardly to the full line position N thereof (Fig. 11) to shift the valve member 229 back again to the position thereof shown in Fig. 8, whereupon the valve element 234 closes the annular passage 223 in housing 214 and not only interrupts the flow of fluid under pressure into the cylinder 53 through the conduit 225 to stop further movement of the piston 65, but also prevents return flow of fluid from the cylinder through the conduit 225 and dropping of the elevator. Feeding of sheets one after another from the top of the pile may now be resumed through the action of the sheet separating and forwarding devices, during which action intermittent elevation of the elevator and pile of sheets by the plunger pump 34 is continued until it is again necessary to load the elevator at which time the above described operations for rapidly lowering and raising the elevator are repeated.

It is to be noted that since the rotary fluid pump 209 is of the constant displacement type, said pump will deliver a constant volume of fluid under pressure into the cylinder 53 when connected therewith to rapidly lower and raise the elevator. Due, however, to the fact that the fluid contacting area of the piston 65 at the right side thereof (Fig. 8) is reduced by the area of the piston rod 66, the speed of movement of the piston 65 toward the right hand end of the cylinder 53 to effect raising of the elevator and pile of sheets thereon, while quite rapid, is less than the speed of movement of the piston toward the left hand end of the cylinder to effect lowering of the elevator to the bottom of the feeder for reception of the pile of sheets. In this manner the elevator is quickly lowered to the bottom of the feeder to receive a pile of sheets and thereafter rapidly raised to bring said pile to the proper feeding level with resulting decrease in loading time and increase in output of the feeder.

It will further be noted that the auxiliary frame 20 supports the feeder driving and operating means, the tubular shafts 152, 153, the rotary air controlling valve mechanism, the rotary vacuum controlling valve mechanism, and the feed and drop roller mechanism, all of which may be bench assembled and then hoisted as a unit into proper position on the feeder frame, thus decreasing feeder erecting time.

Referring now to Figs. 12 to 23 inclusive of the drawings, which illustrate another embodiment of the present invention, the feeder therein shown, while capable of general use, is particularly adapted for feeding large and heavy metal sheets to coating machines, slitters, and other instrumentalities acting on such sheets.

As shown in Figs. 12 to 13^a, the various movable parts of this feeder as well as certain stationary parts thereof are mounted on a frame comprised by front uprights indicated broadly at 249 and rear uprights 250 connected together

by side members indicated broadly at 251. These front uprights 249 and side members 251 are each comprised by a pair of steel plates 252, 253 and 254, 255 respectively, the plates 254, 255 being secured to or formed integrally with the plates 252, 253 at the tops thereof. The plates 252, 253 of each front upright 249 are spaced apart by a vertically extending bar 256 and spacers 257, said plates, bar and spacers being, in turn, bolted together by bolts 258. The plates 254, 255 of the side members 251 are spaced apart by the upper ends of the rear uprights 250 which extend between said plates and are bolted or otherwise suitably secured thereto. The front uprights 249 are bolted or otherwise suitably secured to the machine foundation and connected together by a pair of spaced apart cross beams 259, 260 and a third cross beam 261 all bolted or otherwise suitably secured to the plates 253 of said uprights. The rear uprights 250 are also bolted or otherwise suitably secured to the machine foundation and connected together at the tops thereof by a tubular stay shaft 262 bolted or otherwise suitably secured to the plates 255 of the side members 251. The cross beams 259 and 261 have bolted or otherwise suitably secured thereto a metal apron or plate 263 against which the front side of a supply or pile of metal sheets 264 bears during elevation of the same by mechanism to be hereinafter described.

Referring now more particularly to Figs. 12a and 14, the drive for the feeder is preferably comprised by a chain 265 driven from any suitable source of power (not shown) and passing around a sprocket 266 which is fixed on the outwardly projecting end of a shaft 267. This shaft 267 extends transversely of the feeder and is journaled in suitable bearings in the plates 252, 253 and spacer bars 256 of the front uprights 249. Fixed on the shaft 267 is a spur pinion 268 which meshes with a spur gear 269 that is journaled on a stud 270 secured in any suitable manner on the adjacent front upright 249. Secured to or formed integrally with the spur gear 269 is a spur pinion 271 which meshes with a spur gear 272 that is fixed on a cam shaft 273. This cam shaft 273 extends transversely of the feeder and is journaled in suitable bearings in the plates 252, 253 and spacer bars 256 of the front uprights 249. The cam shaft 273 is utilized to operate various parts of the feeder to be herein-after described. The pile of sheets 264 is supported on a pile elevator which is operated by hydraulically actuated means. Said pile elevator and hydraulically actuated operating means therefor are, in accordance with another aspect of the present invention, preferably mounted and constructed as follows.

The pile elevator is comprised by channel shaped side members 274, 275 (Figs. 12 to 13a) connected together by transversely extending I-beams 276 which are welded or otherwise suitably secured to said side members. Welded or otherwise suitably secured to the I-beams 276 at intervals therealong are channel members 277 having journaled therein rollers 278 on which the pile of sheets may be freely moved into proper position on the elevator. Accordingly, the pile of sheets 264 is placed on a skid 279 and the latter and pile of sheets thereon are then run into the feeder through the rear thereof and on the elevator by plates 280 interposed between said skid and the rollers 278.

Connected with the elevator side member 274

at the forward end thereof is one end of a cable 281 (Figs. 12a and 13a) which extends upwardly and forwardly around a suitably grooved sheave 282 disposed between the plates 252, 253 of the adjacent front upright 249 and journaled thereon as at 283. Connected with the rear end of the elevator side member 274 is one end of a cable 284 (Figs. 12 and 13a) which extends upwardly therefrom and passes around a suitably grooved sheave 285 disposed between the plates 254, 255 of the adjacent side member 251 at the rear thereof and journaled thereon as at 286. From the sheave 285 the cable 284 extends forwardly between the plates 254, 255 and then passes over and around the sheave 282. From the sheave 282 the cables 281 and 284 extend downwardly between the plates 252, 253 of the adjacent front upright 249 to the bottom of the feeder at which point said cables pass under and around a suitably grooved sheave 287 through a suitable opening formed in the plate 253 into which said sheave projects. The sheave 287 is journaled on a pin 288 secured in any suitable manner in brackets 289 that are disposed on opposite sides of said sheave and bolted or otherwise suitably secured to the cross beams 259, 260.

From the sheave 287 the cables 281, 284 extend transversely of the feeder beneath a horizontally arranged hydraulic cylinder 290 (Fig. 13a) and have their free corresponding ends secured, as indicated at 291, 292, respectively (Fig. 15), to the lower end of a strong metal plate 293. This plate 293 is engaged over the reduced threaded portion 294 (Figs. 15 and 16) formed on the outer end of a piston rod 295 and is secured to said piston rod by a nut 296 having threaded engagement with said reduced portion. The piston rod 295 extends into the hydraulic cylinder 290 and has formed on the opposite end thereof a piston head 297 that is slidably engaged with said cylinder. The hydraulic cylinder 290 is disposed between the cross beams 259, 260 and is bolted or otherwise suitably secured to the tops thereof through the medium of brackets 298, 299 formed integrally with the heads 300, 301, respectively, on opposite ends of said cylinder. The heads 300, 301 and hydraulic cylinder 290 therebetween are clamped together as by threaded rods 302. The piston rod 295 passes through the head 300 and through a suitable packing gland 303 that is bolted or otherwise suitably secured to said head.

Connected with the elevator side member 275 at the forward end thereof is one end of a cable 304 (Fig. 13) which extends upwardly and forwardly around a suitably grooved sheave 305 disposed between the plates 252, 253 of the adjacent front upright 249 and journaled thereon as at 306. Connected with the rear end of the elevator side member 275 is one end of a cable 307 which extends upwardly therefrom and passes around a suitably grooved sheave 308 disposed between the plates 254, 255 of the adjacent side member 251 at the rear thereof and journaled thereon as at 309. From the sheave 308 the cable 307 extends forwardly between the adjacent plates 254, 255 and then passes over and around the sheave 305. From the sheave 305 the cables 304 and 307 extend downwardly between the plates 252, 253 of the adjacent front upright 249 to the bottom of the feeder at which point said cables pass under and around a suitably grooved sheave 310 through a suitable opening provided in the plate 253 into

which said sheave projects. The sheave 310 is journalled on a pin 310' (Fig. 23) which is secured in brackets 311 (Fig. 13) that are disposed on opposite sides of said sheave and bolted or otherwise suitably secured to the cross beams 259, 260.

From the sheave 310 the cables 304, 307 extend transversely of the feeder to the opposite side thereof beneath the hydraulic cylinder 290 and then pass under and around a suitably grooved sheave 312 (Figs. 12^a, 13^a and 15) that is disposed adjacent the sheave 287 and journalled on the pin 288. From the sheave 312 the cables 304, 307 extend back over the hydraulic cylinder 290 and have their free corresponding ends secured, as indicated at 313, 314, respectively, to the upper end of the plate 293. As shown in Fig. 15, the plate 293 is angularly disposed on the piston rod 295 so that the cables 281, 284 and 304, 307 extend in substantially a straight line from the sheaves 287, 312, respectively, to said plate. It will thus appear that when the piston 297 is advanced in the hydraulic cylinder 290 toward the left as viewed in Fig. 23, corresponding movement will be imparted to the piston rod 295 and plate 293 thereon, and those portions of the cables 281, 284 and 304, 307 extending between said plate and the sheaves 287, 312 will be lengthened resulting in raising the elevator and pile of sheets thereon. When the piston, the piston rod and the plate are advanced toward the right as viewed in Fig. 23, said portions of the cables will, due to the weight of the elevator, become shortened and the elevator will be lowered. Delivery of fluid under pressure into the hydraulic cylinder 290 to advance the piston 297 in opposite directions is effected and controlled by mechanism preferably mounted, constructed and operated as follows.

Supported on the machine foundation at the front of the feeder and bolted or otherwise suitably secured to the cross beam 260 through the medium of brackets 315 is a platform 316 (Figs. 12^a to 13^a). Secured in any suitable manner to the platform 316 on the under side thereof is a tank 317 adapted to contain a supply of oil, water or other suitable motive fluid as indicated at 318 (Fig. 16). Secured to the platform 316 is a conduit 319 having one end extending through said platform and into the fluid supply tank 317 and the opposite end connected with the inlet side of a rotary fluid pump 320 that is bolted or otherwise suitably secured to the platform 316 at the top thereof. This rotary fluid pump 320 is of the constant displacement type and is driven continuously and at constant speed by an electric motor 321 (Fig. 13^a) through a coupling 322 connecting the armature shaft 323 of said motor with the shaft 324 of said pump. This electric motor 321, which is connected with a suitable source of current and controlled for starting and stopping purposes by suitable switch means (not shown), is bolted or otherwise suitably secured to the platform 316 in line with the rotary fluid pump 320.

Upon rotation of the rotary fluid pump 320 fluid is drawn from the supply tank 317 through the conduit 319 and forced out through a conduit 325 having one end connected with the exhaust side of said pump (Figs. 13, 13^a and 16). The opposite end of this conduit 325 is connected with the inlet side of a pressure relief valve 326 which is supported by, and connected with, a by-pass conduit 327 that is secured to the

platform 316 and extends therethrough into the fluid supply tank 317. This pressure relief valve 326 is of a well known type needing no detail description, herein, except to say that its purpose is to open and permit the fluid to flow from the pump 320 back to the supply tank 317 through the conduit 327 when the fluid pressure, for any reason, exceeds a predetermined amount, thus preventing damage to the hydraulic system.

Under normal conditions, the fluid drawn from the supply tank 317 by the rotary pump 320 flows through the pressure relief valve 326 and into a housing 328 through a conduit 329 having one end connected with said housing and the opposite end connected with said pressure relief valve. This housing 328 forms part of a fluid controlling valve unit indicated broadly at 330 which is bolted or otherwise suitably secured to a transversely extending bar 331 (Figs. 13 and 13^a). The bar 331 is bolted or otherwise suitably secured at opposite ends thereof to short bars 332 that are bolted or otherwise suitably secured to a pair of transversely spaced, forwardly extending plates 333 which, in turn, are bolted or otherwise suitably secured to the cross beams 259, 260. The housing 328 of valve unit 330 has formed therein chambers and passages such as shown, for example, in Figs. 16, 19 and 20 for receiving and distributing the fluid under pressure to either end of the hydraulic cylinder 290, or back to the fluid supply tank 317 as hereinafter described.

Referring now more particularly to Fig. 16, the end of the conduit 329 connected with the housing 328 communicates with a passage 334 which is formed in said housing and terminates in an annular passage 335 that surrounds a cylindrical bore 336 provided in the housing. The cylindrical bore 336 extends the length of the housing 328 and is closed at its ends by caps 337, 338 that are bolted or otherwise suitably secured to opposite ends of said housing. Surrounding the cylindrical bore 336 and suitably spaced therealong are annular passages 339, 340 which terminate in a chamber 341 that is formed in the housing 328 and has connected therewith one end of a conduit 342 the opposite end of which is connected with the by-pass conduit 327. Disposed between the annular passages 335, 340 and surrounding the cylindrical bore 336 is an annular passage 343 which terminates in a passage 344 that is also formed in the housing 328. This passage 344 has connected therewith one end of a conduit 345 the opposite end of which is connected with the cylinder head 301 of the hydraulic cylinder 290. The conduit 345 communicates with the interior of the hydraulic cylinder 290 through a port 346 formed in the cylinder head 301.

Surrounding the cylindrical bore 336 in housing 328 and disposed between the annular passages 335, 339 in said housing are suitably spaced annular passages 347, 348 which terminate in a chamber 349 also formed in the housing. This chamber 349 has connected therewith one end of a conduit 350 the opposite end of which is connected with the cylinder head 300 of the hydraulic cylinder 290 and communicates with the interior thereof through a port 351 formed in said head. Slidably mounted in the cylindrical bore 336 of housing 328 is a valve member 352 provided with reduced portions 353, 354 and 355, the reduced portion 354 forming balanced valve elements 356 and 357.

During normal operation of the feeder and with the pile of sheets in proper feeding position, the valve member 352 will be positioned as shown in Fig. 16 wherein it will be noted that the annular passage 343 is closed by the valve element 357, and that the annular passage 335 is open to the chamber 341 through the reduced portion 354 of valve member 352, the annular passage 348, the chamber 349, the annular passage 347, the reduced portion 353 of the valve member, and the annular passage 339. Under these conditions fluid under pressure forced into the housing 328 by the rotary pump 320 cannot enter the conduit 345 to effect actuation of the piston 291 in the hydraulic cylinder 290 and raising of the elevator thereby. Also, since the annular passage 335 is at this time open to the chamber 341, as previously described, the pressure of the fluid is reduced and said fluid will not flow into the conduit 350 but, instead, flows into the chamber 341 and returns to the fluid supply tank 317 through the conduit 342 and by-pass conduit 327. It will further be noted that when the annular passage 343 is closed by the valve element 357 return flow of fluid from the hydraulic cylinder 290 through the conduit 345 is prevented thus holding the elevator and pile of sheets thereon in raised position.

As sheets are fed off the top of the pile, however, by separating and forwarding means hereinafter described, the height of the pile decreases and when a sufficient number of sheets are so fed it becomes necessary to raise the elevator and pile of sheets thereon in order to keep the top of said pile at a predetermined level for the operation of said means. This raising of the elevator and pile of sheets thereon at certain intervals during operation of the feeder is, in accordance with another aspect of the present invention, controlled by vacuum actuated means preferably mounted, constructed and operated as follows.

Extending transversely of the feeder at the top thereof is a tubular shaft 358 (Figs. 12, 13 and 13a) having welded or otherwise suitably secured to opposite ends thereof plates 359 which, in turn, are bolted or otherwise suitably secured to the plates 253, 255 of the front uprights 249 and side members 251, respectively. Bolted or otherwise suitably secured to the plates 255 of side members 251 are downwardly extending bars 360. Welded or otherwise suitably secured to the tubular shaft 358 on the underside thereof are transversely spaced, forwardly extending plates 361 which have bolted or otherwise suitably secured thereto downwardly extending bars 362 similar to the bars 360. Pivoted, as at 363, on the lower ends of the bars 360, 362 are two frames indicated broadly at 364, 365 each comprised by a pair of side members 366 and a rear cross member 367 mounted on said side members and adjustable therealong to various positions. The frames 364, 365 are supported at the rear thereof by pins 368 that are secured in the rear uprights 250 and in the lower ends of bars 369 which are welded or otherwise suitably secured to the tubular stay shaft 262 and extend downwardly therefrom. Disposed between the frames 364, 365 is a cross bar 370 which is mounted on, and slidably along, the inner side members 366 of said frames.

As stated above, the raising of the elevator and pile of sheets thereon at certain intervals during operation of the feeder is controlled by vacuum actuated means, the source of vacuum for this purpose and the driving means therefor being

preferably mounted, constructed and operated as follows. Fixed on the armature shaft 323 of electric motor 321 is a sprocket 371 (Fig. 13a) around which passes a chain 372 that also passes around a sprocket 373 fixed on the shaft 374 of a vacuum pump 375. The vacuum pump 375 is bolted or otherwise suitably secured to the platform 316 at the top thereof. Connected with the vacuum side of the pump 375 is one end of a conduit 376 (Figs. 13 and 13a) the opposite end of which is connected with the tubular shaft 358 wherein vacuum will thus be continuously created for operation of the vacuum actuated parts of the feeder that will be later described.

The tubular shaft 358 has connected therewith one end of a flexible conduit 377 (Fig. 13) the opposite end of which is connected with a valve housing 378. This valve housing 378 is mounted in a bracket 379 which is secured to, and adjustable along, the cross bar 370 as by a thumb screw 380 or the like. The bracket 379 is provided on the front thereof with a pair of clamps 381 one of which is secured to the bracket by a machine screw 382. The other clamp 381 is secured to the bracket 379 by an adjusting screw 383 provided with a handle 384. The clamps 381 engage opposite sides of the valve housing 378 and provide for vertical adjustment of said valve housing on the bracket 379.

Slidably mounted in the housing 378 is a valve 385 (Figs. 16 to 18) the stem of which projects downwardly through the housing and is provided on the lower end with a socket 386 in which is freely mounted a ball 387 of steel, glass or other non-yielding material that rests on the top of the pile of sheets 264. The valve 385 is provided with reduced portions 388, 389 and 390 suitably spaced therealong. The valve housing 378 is provided in the bore thereof with a chamber 391 formed by the upper and lower ends of spaced bushings 392, 393, and a second chamber 394 formed by the upper end of the bushing 393 and the lower end of a third bushing 395 spaced therefrom. The housing 378 is further provided with lower and upper relief ports 396, 397 which communicate with the bore in said housing through the bushings 392, 395, respectively, and open outwardly to atmosphere through one side of the housing. Displacement of the valve 385 from the housing 378 is prevented by a disk or washer 398 which is bolted or otherwise suitably secured to said valve at the top thereof.

Connected with the housing 378 and communicating with the chamber 391 therein, is one end of a flexible conduit 399 (Figs. 13 and 16) the opposite end of which is connected with one end of a conduit 400 supported in any suitable manner on the feeder frame. The opposite end of this conduit 400 is connected with one end of a conduit 401 which is formed in, and extends through, a bracket 402 (Figs. 13a, 16 and 21) that is bolted or otherwise suitably secured to the bar 331 and to one side of the fluid controlling valve unit 330. Connected with the opposite end of the conduit 401 is one end of a flexible conduit 403 the opposite end of which is connected with the cover plate 404 provided on one end of a small pneumatic cylinder 405. The conduit 403 communicates with the interior of the pneumatic cylinder 405 through a port 406 formed in the cover plate 404. The pneumatic cylinder 405 is bolted or otherwise suitably secured to the bar 331 at one side of the bracket 402 and is provided on the opposite end with a cover plate 407. The cover plates 404, 407 and the pneumatic

cylinder 405 therebetween are clamped together by threaded rods 409 or the like (Fig. 22). Connected with the housing 378 and communicating with the chamber 394 therein, is one end of a flexible conduit 409 the opposite end of which is connected with one end of a conduit 410 supported in any suitable manner on the feeder frame. The opposite end of this conduit 410 is connected with the cover plate 407 of the pneumatic cylinder 405 and communicates with the 10 interior of said cylinder through a port 411 formed in said cover plate.

Mounted for reciprocation in the pneumatic cylinder 405 is a piston 412 (Fig. 16) comprised by a pair of cups 413 of leather, rubber or similar material spaced apart by a metal disk 414 and engaged over the reduced threaded portion 415 of a piston stem 416. The cups 413 and metal disk 414 are held in position on the piston stem 416 by metal disks 417 and a nut 418. The piston stem 416 extends through the cover plate 404 of the pneumatic cylinder 405 and is provided on the outer end thereof with an enlarged portion 419 in which is threaded one end of a rod 420 that is held against rotation by a lock nut 421. This rod 420 extends into the housing 328 of the fluid controlling valve unit 330 through the head 337 thereof and through a packing nut 422 carried by said head. The opposite end of rod 420 is threaded in the adjacent end of the valve member 352. It will thus appear that when the piston 412 in pneumatic cylinder 405 is reciprocated as hereinafter described, corresponding movement will be imparted to the valve member 352 through the described connections for said valve member with the piston stem 416.

When the top of the pile is at proper height the valve 385 through engagement of ball 387 with the pile will be positioned as shown in Fig. 18 wherein it will be noted that the reduced portion 389 of the valve is in communication with the conduit 377, the chamber 394 and the conduit 409, and that the reduced portion 388 of the valve is in communication with the chamber 391, the conduit 399 and the relief port 396. Under these conditions vacuum is created in the left hand end (Fig. 16) of the pneumatic cylinder 405 through the conduit 410 while the right hand end of said cylinder is opened to atmosphere through the conduits 403, 401, 400, 399 and the relief port 396 to enable actuation of the piston 412 in said cylinder. Vacuum thus created in the left hand end of pneumatic cylinder 405 acts on the piston 412 and draws said piston and the fluid controlling valve member 352 connected therewith to their full line positions shown in Fig. 16 determined by a stop arm 423 which is pivotally mounted as at 424 on the cover plate 404 and engages a block 425 that is secured in any suitable manner to the piston stem 416. Under these conditions the fluid under pressure delivered into the housing 328 by the rotary pump 320 flows into the chamber 341 in said housing and returns to the fluid supply tank 317 as hereinbefore described, and no motion is imparted to the elevator and pile of sheets thereon.

As sheets are fed one after another from the top of the pile, however, and with the ball 387 engaged therewith, the valve 385 will lower by gravity and continue to do so until a sufficient number of sheets have been so fed and said valve has lowered to the position thereof shown in Fig. 17. In this position of the valve 385 it will be noted that the reduced portion 389 of the valve is in communication with the conduit 377,

5 the chamber 391 and the conduit 399, and that the reduced portion 390 of the valve is in communication with the chamber 394, the conduit 409 and the relief port 397. Under these conditions vacuum is created in the right hand end (Fig. 16) of the pneumatic cylinder 405 through the conduits 400, 401, 403 and port 406, while the left hand end of said cylinder is opened to atmosphere through the port 411, the conduits 410, 409 and the relief port 397 to enable actuation of the piston 412 in said cylinder. Vacuum thus created in the right hand end of the pneumatic cylinder 405 acts on the piston 412 and draws said piston toward the right until the metal disk 417 thereof engages an annular stop 426 provided on the cover plate 404.

When the piston 412 is actuated and engaged with the annular stop 426 as aforesaid, the fluid controlling valve member 352 will, through the 15 described connections therefor with the piston stem 416, be shifted from the position thereof shown in Fig. 16 to the position thereof shown in Fig. 19. In this position of the fluid controlling valve member 352 it will be noted that the 20 annular passage 340 in the housing 328 is closed by the valve element 357; that the annular passage 335 is opened to the annular passage 343 through the reduced portion 354 of the valve member, and that the annular passage 335 is 25 closed to the annular passage 348 by the valve element 356. Under these conditions, the fluid under pressure forced into the housing 328 by the rotary pump 320 will flow continuously from the annular passage 335 through the annular 30 passage 343, the passage 344, the conduit 345, the port 346 and into the left hand end of the hydraulic cylinder 290 (Fig. 16). The fluid under pressure so forced into the hydraulic cylinder 290 at the left hand end thereof acts on 35 the left face of the piston 297 and advances or moves said piston toward the right (Fig. 16). During this movement the fluid in the right hand end of the hydraulic cylinder 290 is discharged from said cylinder by the piston and returned to 40 the fluid supply tank 317 through the port 351, the conduit 350, the chamber 349 and annular passages 347, 348 which, at this time, are open to the chamber 341 through the reduced portion 353 of valve member 352 and the annular 45 passage 339. As the piston 297 advances or moves 50 toward the right as aforesaid, corresponding movement will be imparted to the piston rod 295 and plate 293 thereon, and those portions of the cables 281, 284, 304, 307 between said plate and 55 the sheaves 281, 312 will be lengthened resulting in raising of the elevator and pile of sheets until the top of the pile is again at the proper height. The piston rod 295 is guided for right line movement by rollers 427, 428 (Fig. 15) which engage 60 the tops and inner sides, respectively, of the cross beams 259, 260 and are journalled in any suitable manner on a bar 429 that is secured to 65 said piston rod between the nut 296 and the plate 293.

65 As the pile thus raises, the valve 385 also raises until it reaches the position shown in Fig. 18 at which time the reduced portion 389 of the valve establishes communication between the conduits 377 and 409, and the reduced portion 70 388 of the valve establishes communication between the conduit 399 and the relief port 396, thus simultaneously breaking the vacuum in the right hand end of the pneumatic cylinder 405 (Fig. 16) and creating vacuum in the left hand end of said cylinder. Vacuum thus created in

the left hand end of the pneumatic cylinder 405 then acts, as previously described, to draw the piston 412 and the fluid controlling valve member 352 toward the left to their full line positions shown in Fig. 16 determined by engagement of block 425 with stop arm 423. Thereupon the valve element 357 of the valve member closes the annular passage 343 in housing 328 and interrupts the flow of fluid under pressure through conduit 345 and into the hydraulic cylinder 290, thus stopping further movement of the piston 297 and elevator thereby. The fluid under pressure forced into the housing 328 by the rotary pump 320 now flows idly through said housing and back into the supply tank 317 until further elevation of the pile is necessary at which time said pile will again be elevated as previously described.

Prior to separation of the sheets one after another at the rear of the pile by suction separating devices hereinafter referred to, the upper rear portion of the pile is wound at spaced points along the same by compressed air that is directed through vertically disposed blow pipes 430 (Figs. 12, 13 and 13^a). These blow pipes 430 are carried in brackets 431 which are engaged over and slideable along the rear cross members 367 of the pivoted frames 364 and 365. The upper ends of the blow pipes 430 have connected therewith corresponding ends of flexible conduits 432 the opposite ends of which are connected in any suitable manner with the housings 433 of separate rotary valve mechanisms 434. These valve mechanisms 434 are suitably spaced across the feeder and provide equal distribution of compressed air to blow pipes 430 and sheet winding devices hereinafter referred to, and equal distribution of vacuum to sheet separating and forwarding devices which are also hereinafter referred to. The rotary valve mechanisms 434 are bolted or otherwise suitably secured to the plates 361 and to similar plates 435 which are welded or otherwise suitably secured to the tubular shaft 358 and extend forwardly therefrom. The construction and operation of each rotary valve mechanism 434 is the same as that of the rotary valve mechanism disclosed in the United States Patent No. 2,156,648 granted May 2, 1939 to Leonard Baker, George A. Martin and Leo C. Williams, and needs no further detail description herein. The rotary valve mechanisms 434 control the delivery of compressed air to the pile and sheet winding devices, and the making and breaking of vacuum in the sheet separating and forwarding devices.

The feeder is provided with a source of compressed air and driving means therefor which are preferably mounted, constructed and operated as follows. Bolted or otherwise suitably secured to the platform 316 and disposed in line with the vacuum pump 375, is a compressed air pump 436 (Fig. 13^a) which is driven by the electric motor 321 through the chain 372, the sprocket 371 and the sprocket 373 which is secured to the shaft 437 of pump 436 as well as to shaft 374 of pump 375. Connected with the exhaust side of the compressed air pump 436 is one end of a conduit 438 the opposite end of which is connected with a tubular shaft 439. This tubular shaft 439 extends transversely of the feeder at the top thereof and is welded or otherwise suitably secured to, and closed at its opposite ends by, the plates 359. The forwardly extending plates 361, 435 are welded or otherwise suitably secured to the tubular shaft 439.

as well as to the tubular shaft 358 to provide an additional support for said plates and parts carried thereby. Air under pressure will, through the described connection between the compressed air pump 436 and the tubular shaft 439, be continuously maintained in the latter which, in turn, is connected with the air sides of the rotary valve housings 433 by flexible conduits 440. The tubular shaft 358 wherein vacuum is continuously created by the vacuum pump 375 as previously described, is connected with the vacuum sides of the rotary valve housings 433 by flexible conduits 441.

Delivery of compressed air to the blow pipes 430 at predetermined intervals is effected by the rotary valves 442 connected with the driving disks 443 that are fixed on the cam shaft 273 which extends loosely through the valve housings 433. The rotary valves 442, during each cycle of operation of the feeder, connect and disconnect the blow pipes 430 with the tubular shaft 439 through the described connections therefor with the valve housings 433.

While the upper rear portion of the pile is being wound as just described, the top sheet of the pile is engaged and lifted at spaced points along the rear edge thereof by vacuum sheet separating devices comprised by cylinders 444 mounted on the brackets 431, and suction cups 445 slidably associated with the cylinders and which are raised and lowered through the making and breaking of vacuum in said cylinders (Figs. 12, 13 and 13^a). These sheet separating devices are constructed and operated in the same manner as the sheet separating devices disclosed in the United States Patent No. 2,156,648 above referred to and need no detailed description herein. It might be pointed out, however, that the cylinders 444 have connected therewith corresponding ends of flexible conduits 446 the opposite ends of which are connected in any suitable manner with the vacuum sides of the rotary valve housings 433. Vacuum is created at the proper time in the cylinders 444 so that the suction cups 445 are actuated in opposite directions to engage and lift the rear edge portion of the top sheet. This is effected by the rotary valves 447 connected with the driving disks 448 that are fixed on the cam shaft 273. The rotary valves 447 during rotation of the same, connect and disconnect the cylinders 444 with the vacuum pump 436 through the described connections therefor with the valve housings 433.

After the top sheet of the pile has been lifted at the rear thereof by the suction cups 445, the lifted sheet is wound at spaced points along and under the same by compressed air that is delivered through vertically disposed blow pipes 449 carried by the brackets 431. The upper ends of the blow pipes 449 have connected therewith corresponding ends of flexible conduits 450 the opposite ends of which are connected in any suitable manner with the air sides of the rotary valve housings 433. Delivery of compressed air at the required predetermined intervals through the blow pipes 449 is effected by the rotary valves 442 which, through continued rotation thereof, connect and disconnect said blow pipes with the tubular shaft 439 through the described connections therefor with the valve housings 433. The compressed air delivered through the blow pipes 449 is directed between the separated sheet and the one therebelow so that said separated sheet is completely lifted from the pile.

When the separated sheet has been wound it is engaged and lifted at spaced points along the front thereof by a plurality of vacuum sheet forwarding devices comprised by cylinders 451 and suction cups 452 that are moved up and down relative to said cylinders through the making and breaking of vacuum therein. These sheet forwarding devices are constructed and operated in the same manner as the sheet forwarding devices disclosed in the U. S. Patent No. 2,156,648 above referred to and need no detailed description herein. It is pointed out, however, that swinging movement is imparted to the sheet forwarding devices to advance the sheets that have been separated from the pile by the sheet separating devices. For this purpose, the cylinders 451 are secured to arms 453 which, in turn, are fixed on a rock shaft 454 that extends transversely of the feeder and is journaled in suitable bearings in the downwardly extending bars 360 and 362. The sheet forwarding devices are rocked rearwardly by springs (not shown) having corresponding ends each connected with an arm 455 fixed on the rock shaft 454 and opposite ends connected with the feeder frame. The sheet forwarding devices are rocked forwardly by cams such as indicated at 456 which are fixed on and rotated by the cam shaft 273. Each of these cams engages a cam roller 457 journaled on a cam strap 458 extending over cam shaft 273 and connected with the arm 455.

The making and breaking of vacuum in the cylinders 451 of the sheet forwarding devices is also effected by the rotary valves 447 at proper intervals, and for this purpose the cylinders 451 have connected therewith corresponding ends of flexible conduits 459 the opposite ends of which are connected in any suitable manner with the vacuum sides of the valve housings 433. The operation of the rotary valves 447 is so timed that vacuum is established in the cylinders 451 to move the suction cups 452 into engagement with the top sheet of the pile when the sheet forwarding devices have been swung rearwardly, and vacuum is maintained in cylinders 451 until the sheet forwarding devices have completed their forward movement and delivered the sheet engaged thereby in proper position on a conveyor hereinafter described.

After the uppermost sheet has been separated and forwarded from the pile, it is received by conveying means for carrying said sheet into the machine or instrumentality with which the feeder is associated. This conveying means includes a feed roller 460, drop rollers 461, and conveyor tapes 462 passing around and driven by said feed roller (Fig. 12^a). The feed roller 460 extends transversely of the feeder and is fixed on and driven by the shaft 267. The front portions of the tapes 462 pass around a roller 463 journaled in any suitable manner in brackets 464 which are bolted or otherwise suitably secured to the frame 465 of the coating, slitting or other machine to which the sheets are fed. The tapes 462 also pass under tightening rollers 466 journaled on arms 467 which are adjustably secured on a shaft 468 extending transversely of the feeder and secured against rotation in the plates 253 of the front uprights 249.

The drop rollers 461 are journaled on arms 469 fixed on a rock shaft 470 which extends transversely of the feeder and is journaled in suitable bearings formed in the valve housings 433 and in the plates 253 of the front uprights 249. The drop rollers 461 are raised and lowered by cams

such as indicated at 471 secured to or formed integrally with certain of the valve driving disks 443 and each of which engages a roller 472 journaled on an arm 473 that is fixed on the rock shaft 470.

When the pile of sheets is exhausted or nearly so through intermittent raising of the elevator and the sheet separating and forwarding action of the sheet separating and forwarding devices, the elevator may be quickly lowered to the machine foundation to receive a new pile of sheets and thereafter rapidly raised to bring said new pile of sheets to proper feeding position. This rapid lowering and raising of the elevator is, in accordance with another aspect of the present invention, effected and controlled by mechanism preferably constructed and operated as follows. Bolted or otherwise suitably secured at one side of the feeder on the plate 253 of the adjacent front upright 249 and on the adjacent rear upright 250 are brackets 474, 475, respectively, (Figs. 12, 12^a and 13^a) in which is journaled a rock shaft 476 having fixed on the rear end thereof a handle 477. Fixed on the front end of the rock shaft 476 is an arm 478 having pivotally connected therewith the upper end of a rod 479 the lower end of which is pivotally connected with an arm 480. This arm 480 is fixed on one end of a short shaft 481 which is journaled in a bracket 482 that is bolted or otherwise suitably secured to the plate 253 of the adjacent front upright 249.

The short shaft 481 extends through the bracket 482 and has fixed on the other end thereof an arm 483. Pivotally connected with this arm 483 is one end of a rod 484 the opposite end of which is pivotally connected with the upper arm 485 of a lever 486 (Figs. 16 and 21). This lever 486 is pivotally mounted as at 487 on the bracket 402 and provided with a forked lower arm 488. Pivotally connected with the lower forked end of arm 488 are spaced apart links 489 (Figs. 16, 21 and 22) provided with slots 490 to receive opposite ends of a pin 491 that is secured in any suitable manner in the enlarged end portion 419 of the piston stem 416. The slots 490 in links 489 provide a lost motion connection between the lever 486 and the piston stem 416 to enable automatic actuation of the fluid controlling valve member 352 by the vacuum operated piston 412, as previously described, during normal operation of the feeder.

The arm 485 of lever 486 has mounted thereon a small spring pressed disk valve 492 which normally closes a port 493 that is formed in the bracket 402 and communicates with the conduit 401 in said bracket. The arm 488 of lever 486 is provided with a pin 494 adapted to engage a beveled edge 495 formed on the stop arm 423 and lift the latter out of the path of the block 425 when said lever is actuated as hereinafter described. The stop arm 423 is provided with a slot 496 open at one end and into which the pin 494 extends upon lifting of said arm thereby.

During normal operation of the feeder the handle 477 is disposed in the neutral vertical position thereof shown in Figs. 12 and 13^a. When the pile of sheets is exhausted or nearly so and it is desired to reload the feeder, the elevator may, for this purpose, be quickly lowered to the machine foundation by moving the handle 477 outwardly or toward the right (Fig. 13^a). This movement of the handle 477 rocks the shaft 476 and lowers rod 479 so that the rod 484 is moved

toward the left (Fig. 13^a) and the lever 486 is rocked thereby to the position D shown in dotted lines in Fig. 16. When the lever 486 is rocked as aforesaid, the first effect will be the uncovering of port 493 by the disk valve 492, opening of the right hand end of the pneumatic cylinder 405 to atmosphere, and the lifting of the stop arm 423 out of the path of the block 425 by the pin 494 on arm 488. At about this time the lost motion in the slots 490 will be taken up and the pin 491 will be engaged by the links 489 at the forward ends of the slots 490. Thereupon the fluid controlling valve member 352 and piston 412 connected therewith will be shifted toward the left (Fig. 16) until the metal disk 417 of said piston strikes an annular stop 497 formed on the cover plate 401 of the pneumatic cylinder 405. In the event the handle 477 is moved as aforesaid when the pile controlled valve 385 is in the position thereof shown in Fig. 18 and at which time vacuum is created in the left hand end (Fig. 16) of the pneumatic cylinder 405, as previously described, the piston 412 and fluid controlling valve member 352 connected therewith will be shifted automatically toward the left by 25 vacuum as soon as the stop arm 423 is lifted by the pin 494 out of the path of the block 425 on piston stem 416.

The fluid controlling valve member 352 will thus be shifted manually or automatically as the 30 case may be to the position shown in Fig. 20 wherein it will be noted that the annular passages 347, 348 in housing 328 are opened to the annular passage 335 through the reduced portion 354 of the valve member; that said annular passages 347, 348 are closed to the annular passage 339 by the valve element 356; and that the annular passage 335 is closed to the annular passage 343 by the valve element 357. Under these conditions the fluid under pressure forced 35 into the housing 328 by rotary pump 320 will flow through the annular passages 347, 348, the chamber 349, the conduit 350, the port 351 and into the right hand end of the hydraulic cylinder 290 (Fig. 16). The fluid under pressure so forced into the hydraulic cylinder 290 acts on the right face of the piston 297 and moves said piston quickly toward the left (Fig. 16). During this movement of piston 297 and in the position of the fluid controlling valve member 352 and its valve element 357, shown in Fig. 20, the fluid previously delivered into the left hand end of the hydraulic cylinder 290 is discharged from the cylinder by the piston and returned through the port 346, the conduit 345, the passage 344, the annular passage 343, the bore 336, the annular passage 340, the chamber 341, the conduit 342, and the by-pass conduit 327, into the fluid supply tank 317.

When the piston 297 moves rapidly toward the left (Fig. 16) as previously described, the piston rod 295 and plate 293 thereon likewise move to the left and those portions of the cables 281, 284, and 304, 307 extending from the plate to the sheaves 287, 312 will, due to the weight of the pile elevator, become shortened which results in lowering of the elevator and skid 279 to the bottom of the feeder. As soon as the elevator and skid 279 have been lowered to proper position for reloading the handle 477 is moved inwardly or toward the left (Fig. 13^a) to its vertical or neutral position. Upon movement of the handle 477 toward the left as aforesaid, the rod 479 is raised thus rocking lever 486 toward the left to the full line position thereof shown in Fig. 16. 70 75

At this time the port 493 in bracket 402 is again closed by the disk valve 492, and the stop arm 423 is released by the pin 494. Location of the lever 486 in its normal full line position (Fig. 16) and the handle 477 in its normal vertical or neutral position (Fig. 12) is accomplished by a spring pressed ball 498 (Fig. 21) carried in the arm 488 of lever 486 and engaging a depression or socket 499 formed in the bracket 402.

10 When the handle 477 is moved toward the left (Fig. 13^a) to stop lowering movement of the elevator, the fluid controlling valve member 352 is shifted toward the right to the position shown in Fig. 16 at which time the fluid under pressure forced into the housing 328 is directed back to the fluid supply tank 317, as hereinbefore described, the piston 297 is stopped, and the pile controlled valve 385, through lowering of the skid 279 with the elevator, drops to its lowermost 15 position as shown in Fig. 16 and closes the conduit 377 so that vacuum cannot be created in the pneumatic cylinder 405 to actuate the piston 412 and fluid controlling valve member 352 while the new pile of sheets is being loaded on the elevator. The elevator is then loaded in the usual manner with the new pile of sheets through the rear of the feeder.

The elevator having been lowered and stopped in its proper position for reloading, and the new pile of sheets having been placed on the elevator, the latter and the pile of sheets are rapidly elevated until the top of the pile is brought into proper position for the normal sheet feeding operations. For this purpose the handle 477 is moved inwardly or to the left (Fig. 13^a) from its vertical or neutral position to raise the rod 479 and rock the lever 486 to the position U thereof shown in dotted lines in Fig. 16, at which time the port 493 in bracket 402 is again uncovered

40 by the disk valve 492. The fluid controlling valve member 352 is thus shifted from the position thereof shown in Fig. 16 to the position thereof shown in Fig. 19 thus connecting the rotary fluid pump 320 with the left hand end (Fig. 16) of the hydraulic cylinder 290 through the housing 328, the conduit 345 and the port 346, as hereinbefore described in connection with normal operation of the feeder. The fluid under pressure thus admitted into the left hand end of the hydraulic cylinder 290 then acts on the left face of the piston 297 and advances or moves said piston rapidly toward the right to raise the elevator and new pile of sheets thereon until the top of the pile reaches the proper level for feeding of the sheets one after another therefrom. During this movement the fluid previously admitted into the right hand end of the hydraulic cylinder 290 is discharged therefrom by the piston 297 and returned to the fluid supply tank 317 through the port 351, the conduit 350, the housing 328 and the conduits 342, 327, as hereinbefore described in connection with normal operation of the feeder.

As the new pile thus raises, the handle 477 is again moved outwardly or to the right (Fig. 13^a) to its normal vertical or neutral position, thus rocking the lever 486 to the normal full line position thereof shown in Fig. 16 determined through engagement of ball 498 in said lever with the depression or socket 499 in bracket 402. At this time the port 493 in bracket 402 is again closed by the disk valve 492 in lever 486, but due to the lost motion in the slots 490 of links 489, no motion will be imparted to the fluid controlling valve member 352. When the top of the

pile reaches the proper feeding level, however, and the pile controlled valve 385 is accordingly raised by said pile to the position thereof shown in Fig. 18, communication will again be established between the conduit 371 and the conduits 409, 410. Vacuum will thus be created in the left hand end (Fig. 16) of the pneumatic cylinder 405 which then acts to draw the piston 412 toward the left to the full line position thereof shown in Fig. 16 determined through engagement of block 425 with the stop arm 423. The fluid controlling valve member 352 will thus be shifted by vacuum from the position thereof shown in Fig. 19 to the position thereof shown in Fig. 16 whereupon the valve element 351 of the valve member closes the annular passage 343 in housing 328 to interrupt the flow of fluid under pressure into the hydraulic cylinder 290 through the conduit 345 and thereby stop the piston 297 and further raising of the elevator thereby. The pin 491 in the enlarged end portion 419 of the piston stem 416 will now be disposed at the rear ends of the slots 490 in links 489 to again enable automatic control of the fluid controlling valve member 352 and the elevator by the pile controlled valve 385 as hereinbefore described. Feeding of sheets one after another from the top of the new pile may now be resumed and continued through the action of the sheet separating and forwarding devices and intermittent raising of the elevator and pile of sheets until it is again necessary to load the elevator at which time the above described operations for quickly lowering and rapidly raising the elevator are repeated.

Instead of supplying fluid under pressure into the hydraulic cylinder 290 to effect lowering of the elevator 274, 275, 276 to loading position, said elevator may, due to its own weight, be quickly lowered to the machine foundation solely by gravity. Should this be desirable, the conduit 350 instead of being connected with cylinder 290 is connected with the fluid supply tank 317 through the by-pass conduit 327 as shown, for example, in dotted lines in Fig. 16. The port 351 in head 300 then serves as a relief port for the hydraulic cylinder 290 to permit the air in said cylinder to escape when the piston 297 is advanced or moved forwardly to raise the elevator, and to prevent the creation of vacuum in the cylinder when the piston is retracted or moved rearwardly to effect lowering of the elevator.

Under these conditions, and when the fluid controlling valve member 352 is shifted to the position thereof shown in Fig. 20 as previously described, the fluid in the left hand end (Fig. 16) of the hydraulic cylinder 290 will be released by the valve element 351 through opening of the passages 340, 343 in housing 328, whereupon the elevator due to its own weight, will drop solely by gravity to the machine foundation or loading position. During this time, the fluid under pressure forced into the housing 328 by the rotary pump 320 flows through said housing, the conduit 350 and back into the fluid supply tank 317.

As the elevator thus drops by gravity to the machine foundation, the piston 297 will be moved toward the left (Fig. 16) by the cables 281, 284, 304, 307, and the fluid in the hydraulic cylinder 290 will be forced by the piston back into the fluid supply tank 317 through the port 346, the conduit 345, the housing 328 and the conduits 342, 327, the resistance created by the fluid in passing through said port, said housing and said

conduits controlling the rapidity of the downward movement of the elevator. The elevator may now be loaded with a new pile of sheets and thereafter raised hydraulically upon manually shifting the fluid controlling valve member 352 to the position thereof shown in Fig. 19 as hereinbefore described.

The present description and its accompanying drawings set forth with more or less particularity two embodiments of the present invention, but it is to be expressly understood that said invention is not limited to said embodiments or otherwise than by the terms of the appended claims.

15. What we claim is:

1. In a machine of the type having means for supporting a pile of sheets, the combination of upper and lower rotatably mounted means, four flexible elements connected with the pile supporting means and passing around said upper and lower rotatably mounted means, hydraulically actuated means for operating said four flexible elements and said pile supporting means, and pile engaged means for controlling the operation of said hydraulically actuated means.

2. In a machine of the type having means for supporting a pile of sheets, the combination of upper and lower rotatably mounted means, four flexible elements passing around said upper and lower rotatably mounted means, horizontally disposed hydraulically actuated means for drawing said four flexible elements over the upper and lower rotatably mounted means and thereby operating said pile supporting means, and pile engaged means for controlling the operation of said hydraulically actuated means.

3. In a machine of the type having means for supporting a pile of sheets, the combination of upper and lower rotatably mounted means, four flexible elements connected with the pile supporting means and passing around said upper and lower rotatably mounted means, horizontally disposed hydraulically actuated means extending transversely of the machine adjacent the lower rotatably mounted means, said hydraulically actuated means being operatively associated with the four flexible elements and adapted to operate said four flexible elements and said pile supporting means, and pile engaged means for controlling the operation of said hydraulically actuated means.

4. In a machine of the type having means for supporting a pile of sheets, the combination of upper means mounted for rotation about spaced parallel axes extending transversely of the machine, lower means mounted for rotation about spaced parallel axes extending longitudinally of the machine, four flexible elements connected with the pile supporting means, the four flexible elements passing around the upper and lower rotatably mounted means and having portions extending transversely of the lower part of the machine, hydraulically actuated means operatively associated with the transversely extending portions of the four flexible elements and adapted to operate said four flexible elements and said pile supporting means, and pile engaged means for controlling the operation of said hydraulically actuated means.

5. In a machine of the type having means for supporting a pile of sheets, the combination of four longitudinally and laterally spaced upper rotatable means, two laterally spaced lower means rotatable about axes extending at right angles to the axes of rotation of the upper means, four

flexible elements connected with the pile supporting means and passing around the four upper rotatable means, two of the flexible elements passing around one of the lower rotatable means and the other two flexible elements passing around both of said lower rotatable means, hydraulically operated means operatively associated with all four of the flexible elements and adapted to operate said four flexible elements and said pile supporting means, and pile engaged means for controlling the operation of said hydraulically operated means.

6. In a machine of the type having means for supporting a pile of sheets, the combination of upper and lower rotatably mounted means, flexible elements connected with the pile supporting means and passing around said upper and lower rotatably mounted means, hydraulically actuated means for operating said flexible elements and said pile supporting means, and pile engaged means for controlling the operation of said hydraulically actuated means.

7. In a machine of the type having means for supporting a pile of sheets, the combination of hydraulically actuated means for operating said pile supporting means, pneumatically actuated means for controlling the operation of said hydraulically actuated means, and pile engaged means for controlling the operation of said pneumatically actuated means.

8. In a machine of the type having means for supporting a pile of sheets, the combination of upper and lower rotatably mounted means, flexible elements connected with the pile supporting means and passing around said upper and lower rotatably mounted means, hydraulically actuated means operatively associated with the flexible elements and intermittently operated or rapidly and continuously operated to intermittently or rapidly and continuously operate said flexible elements and said pile supporting means, and means for selectively rendering said hydraulically actuated means effective to operate intermittently or rapidly and continuously.

9. In a machine of the type having means for supporting a pile of sheets, the combination of upper and lower rotatably mounted means, flexible elements connected with the pile supporting means and passing around said upper and lower rotatably mounted means, hydraulically actuated means operatively associated with the flexible elements, the hydraulically actuated means being intermittently operated in one direction to likewise operate the flexible elements and the pile supporting means or said hydraulically actuated means being rapidly and continuously operated in either direction to likewise operate said flexible elements and said pile supporting means, and pile engaged means and manually controlled means for selectively rendering the hydraulically actuated means effective to operate intermittently in one direction or rapidly and continuously in either direction.

10. In a machine of the type having pile supporting means and vertically disposed front pile guiding means, the combination of a pair of side frames each comprised by spaced members, rotatable devices journaled on the side frames between the spaced members thereof and disposed forwardly of the vertical line of said front pile guiding means, flexible elements connected with the pile supporting means, said flexible elements extending between the spaced members of said side frames forwardly of the front pile guiding means and passing around said rotatable devices, 75

and means for operating the flexible elements and said pile supporting means.

11. In a machine of the type having means for supporting a pile of sheets, the combination of a cylinder having a piston therein for operating the pile supporting means, pump means for supplying fluid intermittently into the cylinder to intermittently operate the piston and the pile supporting means, and other pump means for supplying fluid continuously into said cylinder to continuously operate said piston and said pile supporting means.

12. In a machine of the type having means for supporting a pile of sheets, the combination of a cylinder having a piston therein for operating the pile supporting means, pump means for supplying fluid intermittently into the cylinder to intermittently operate the piston and the pile supporting means, other pump means for supplying fluid continuously into the cylinder to continuously operate said piston and said pile supporting means, and means for selectively rendering each of said pump means effective or ineffective to supply fluid into said cylinder.

13. In a machine of the type having means for supporting a pile of sheets, the combination of a cylinder having a piston therein for operating the pile supporting means, pump means for supplying fluid intermittently into the cylinder to intermittently operate the piston and the pile supporting means, other pump means for supplying fluid continuously into said cylinder to continuously operate said piston and said pile supporting means, and means for selectively rendering each of said pump means effective or ineffective to supply fluid into said cylinder.

14. In a machine of the type having means for supporting a pile of sheets, the combination of a cylinder having a piston therein for operating the pile supporting means, pump means for supplying fluid into said cylinder to operate said piston and said pile supporting means, control means for said pump means to start and stop the same, and pile engaged means controlling the operation of said second named pump means.

15. In a machine of the type having means for supporting a pile of sheets, the combination of a cylinder having a piston therein for operating the pile supporting means, pump means for supplying fluid into the cylinder to operate the piston and the pile supporting means pneumatically operated means engageable with and disengageable from said pump means to stop and start the same, and pile engaged means controlling engagement of said pneumatically operated means with and disengagement of the same from the pump means.

16. In a machine of the type having means for supporting a pile of sheets, the combination of a cylinder having a piston therein for operating the pile supporting means, a reciprocating pump for supplying fluid into said cylinder to operate said piston and said pile supporting means, control means engageable with and disengageable from the pump to prevent or provide for reciprocation thereof, and pile engaged means controlling engagement of said control means with and disengagement of the same from said pump.

17. In a machine of the type having means for supporting a pile of sheets, the combination of a cylinder having a piston therein for operating the pile supporting means, intermittently operated pump means for supplying fluid into the cylinder at one side of the piston to operate the latter in

one direction, continuously operated pump means for supplying fluid into the cylinder at one side or the other of the piston to operate it in one direction or the other, pile engaged means controlling operation of the piston by the intermittently operated pump, and valve means controlling operation of the piston by the continuously operated pump.

18. In a machine of the type having means for supporting a pile of sheets, the combination of upper and lower rotatably mounted means, a cylinder disposed horizontally adjacent the lower rotatably mounted means, four flexible elements passing around said upper and lower rotatably mounted means and having corresponding ends connected with the pile supporting means and opposite ends fixed or anchored adjacent the horizontally disposed cylinder, a hydraulically operated piston in said cylinder operatively associated with the four flexible elements and adapted to operate said four flexible elements and said pile supporting means, and pile engaged means for controlling the operation of said hydraulically operated piston.

19. In a machine of the type having means for supporting a pile of sheets, the combination of upper and lower rotatably mounted means, a cylinder disposed horizontally adjacent the lower rotatably mounted means, a hydraulically actuated piston in the cylinder, rotatably mounted means carried by the piston, and four flexible elements passing around said upper, lower and piston carried rotatably mounted means, the four flexible elements having corresponding ends connected with the pile supporting means and opposite ends anchored adjacent the horizontally disposed cylinder, said four flexible elements and said pile supporting means being operated by said hydraulically actuated piston.

20. In a machine of the type having pile supporting means, the combination of hydraulically actuated means for operating the pile supporting means, valve means controlling the operation of said hydraulically actuated means, and pneumatically operated means controlling the operation of said valve means.

21. In a machine of the type having pile supporting means, the combination of hydraulically actuated means for operating the pile supporting means, interconnected valve means and pneumatically operated means controlling the operation of said hydraulically actuated means, and pile engaged means controlling the operation of said pneumatically operated means.

22. In a machine of the type having pile supporting means, the combination of hydraulically actuated means for operating the pile supporting means, interconnected valve means and pneumatically operated means controlling the operation of said hydraulically actuated means, and manually operated means for operating said valve means.

23. In a machine of the type having pile supporting means, the combination of hydraulically

actuated means for operating the pile supporting means, interconnected valve means and pneumatically operated means controlling the operation of said hydraulically actuated means, manually operated means for operating the valve means, and a lost motion connection between the manually operated means and the valve means providing for operation of said valve means by said pneumatically operated means without operation of said manually operated means.

10 24. In a machine of the type having pile supporting means, the combination of upper and lower rotatably mounted means, a cylinder, a hydraulically operated piston in the cylinder, and flexible means passing around said upper and lower rotatably mounted means and having corresponding ends connected with said pile supporting means and opposite ends anchored on said piston.

15 25. In a machine of the type having pile supporting means, the combination of upper and lower rotatably mounted means, a horizontally disposed cylinder, a hydraulically operated piston in the cylinder, flexible means passing around said upper and lower rotatably mounted means and having corresponding ends connected with said pile supporting means, and means for anchoring the opposite ends of said flexible means on said hydraulically operated piston.

20 26. In a machine of the type having means for supporting a pile of sheets, the combination of upper and lower rotatably mounted means, flexible elements connected with the pile supporting means and passing around said upper and lower rotatably mounted means, a cylinder, a piston in said cylinder operatively associated with the flexible elements, pump means for supplying fluid into the cylinder to operate said piston, said flexible elements and said pile supporting means, valve means controlling the delivery of fluid into the cylinder by said pump means, and pile engaged means controlling the operation of said valve means and delivery of fluid into the cylinder by said pump means.

25 27. In a machine of the type having means for supporting a pile of sheets, the combination of upper and lower rotatably mounted means, flexible elements connected with the pile supporting means and passing around said upper and lower rotatably mounted means, a horizontally disposed cylinder, a piston in said cylinder and operatively associated with the flexible elements, continuously operated pump means for supplying fluid into the cylinder to operate said piston, said flexible elements and said pile supporting means, valve means movable in one direction to enable delivery of fluid into said cylinder by said pump means and movable in the opposite direction to interrupt delivery of fluid into the cylinder, and pile engaged means controlling movement of said valve means in said first and last named directions.
